SHIRRING MACHINE

Clifford E. Ives, Chicago, Ill., assignor to Tee-Pak, Inc.,
Chicago, Ill., a corporation of Illinois
Filed Sept. 19, 1960, Ser. No. 57,957
34 Claims. (Cl. 17—42)

This invention relates, generally, to the shirring of thin walled cellulosic sausage casings and the like and it has particular relation to the automation thereof.

Among the objects of this invention are: To provide for automatically converting a tubular thin walled cellulosic casing of indefinite length into a plurality of shirred strands of the casing of definite length in a new and improved manner; to shirr the casing onto a floating mandrel and then to transfer it to a receiving mandrel that is separate and distinct from the floating mandrel; to shirr the casing continuously on the floating mandrel; to employ a plurality of receiving mandrels and to mount them for endwise movement on and bodily movement with a turret that is rotatable about an axis parallel to the longitudinal axis of the floating mandrel; to index the turret for positioning the receiving mandrels, one by one, in endwise alignment with the floating mandrel; to shift the receiving mandrel in alignment with the floating mandrel into endwise engagement therewith to support it against endwise, sidewise, and rotary movement about its longitudinal axis when the clamp means otherwise holding it against such movement is disengaged therefrom; to supply air under pressure through the floating mandrel for inflating the unshirred casing and to continue the supply of air under pressure through the receiving mandrel while supporting the floating mandrel; to shirr the casing against compaction means positioned adjacent the floating mandrel and in close proximity to the point at which the shirring operation takes place; to employ a pair of compaction rolls on opposite sides of the floating mandrel for the compaction means and to rotate them in the direction that the casing is shirred at a peripheral speed equal to the linear speed at which the casing is shirred; to sever a shirred strand of the casing adjacent the compaction means or rolls from the following shirred casing; to separate the folds and pleats of the shirred casing and to extend them for facilitating the severance of the shirred strand and then to contract them to their shirred state; to compress completely the shirred strand on the floating mandrel in the direction in which the strand is shirred against the clamp means which holds it against movement or alternatively to open the clamp means and transfer the uncomplicated strand to the receiving mandrel in supporting engagement with the floating mandrel and to compress it on this receiving mandrel in the direction in which the strand is shirred for the major portion of the total compression; to transfer the shirred and compressed strand from the floating mandrel to the receiving mandrel in supporting engagement therewith; to recompress the strand on the receiving mandrel in the direction opposite to that in which it is shirred on indexing of the turret to move the receiving mandrel out of alignment with the floating mandrel or to complete the compression of the strand in the direction opposite to the direction in which the casing is shirred; to hold the strand under compression while the turret is being indexed to bring the other receiving mandrels into and out of receiving position with respect to the floating mandrel; to doff the completed strand from the receiving mandrel in a position thereof preceding its movement again into strand receiving position; to mount the floating mandrel horizontally and to support the leading end thereof which projects into the unshirred inflated casing by a roll which is rotated in the direction that the casing moves to be shirred at a periph-

2

eral speed equal to the linear speed that the casing moves; and to perform the various operations and functions simultaneously and/or sequentially in definite timed relation to the end that the casing is shirred continuously onto the floating mandrel and the shirred strands are severed, one by one, compressed in the shirring direction, transferred to the receiving mandrels or transferred to the receiving mandrels without being compressed and thereon compressed in the direction of shirring, recompressed in the opposite direction to the shirring direction or further compressed in this opposite direction, held under compression and finally doffed from the receiving mandrels.

In the drawings:

FIGS. 1 and 2, taken together with FIG. 1 being placed to the left of FIG. 2, shows in perspective and somewhat diagrammatically an automatic shirring machine embodying the present invention.

FIG. 3 is a sequence diagram showing the succession of events taking place in the shirring of a strand by the shirring head onto the floating mandrel and the succession of events which takes place as the shirred strand progresses through the shirred casing handling machine.

FIG. 4 is a turret diagram which shows one position of the turret where one of the receiving mandrels is in alignment with the floating mandrel, certain of the receiving mandrels have the shirred strand held in compression thereon and the receiving mandrel, next to be moved into alignment with the floating mandrel, has the strand thereon doffed therefrom.

FIG. 5 is a vertical sectional view, at an enlarged scale, of a typical splice formation at the abutting ends of the flat casing.

FIG. 6 is a view, in side elevation and looking from right to left of the measuring roll as shown in FIG. 2, of one of the supports for the measuring roll and the squeeze roll and parts associated therewith for detecting the presence of a splice.

FIG. 7 is a view in side elevation, looking from right to left, of the construction shown in FIG. 6.

FIG. 8 is a top plan view of the portion of the apparatus shown in FIG. 6, except that the end portion only of the squeeze roll is shown and the operating handle, shown in FIG. 6, is not illustrated.

FIG. 9 shows, diagrammatically, the drive motor and certain of the control elements associated therewith.

FIG. 10 shows, diagrammatically, the circuit connections that are used in conjunction with the apparatus shown in FIG. 9 for the purpose of controlling the operation of the shirring machine shown in FIGS. 1-2, upon the occurrence of a splice in the unshirred casing.

FIG. 11 is a chart which shows various operations that are performed during a period of operation of the casing severing means.

FIG. 12 is a perspective view of the shirred casing severing means or the severing machine, certain parts being broken away in order to show clearly the details of construction.

FIG. 13 is a perspective view showing the relationship between one of the pinch rolls provided with a pinion which is rotated on engagement with a stationary rack.

FIG. 14 is a perspective view showing the details of construction and mode of operation of the holding finger or digger and of the scoring yoke or cutter.

FIG. 15 is an exploded view of the cams and certain of the associated parts of the severing machine shown in FIG. 12.

FIG. 16 is a view showing the relation between the vertical rod which supports the holding finger or digger and the transverse head member which, in part, controls its movement.

FIG. 17 is a view, similar to FIG. 16, showing the rela-

tionship between the rod which carries the scoring yoke or cutter and the transverse head member which, in part, controls its movement.

FIGS. 18 to 27 show the sequence of operations involved in performing a severing operation to sever a stirred strand from the following stirred casing.

FIG. 28 is an elevational view showing the manner in which the connections are made to rotate the support rails on which the carriage is mounted to move the stirred strand along the floating mandrel and to transfer it therefrom to a receiving mandrel.

FIG. 29 is a view, in end elevation, of the construction shown in FIG. 28, the support rails being shown in section, illustrating the positions of the parts when the carriage jaws are in operative position with respect to the floating mandrel.

FIG. 30 is a view, similar to FIG. 29, showing the positions of the several parts when the carriage jaws have been moved upwardly and out of operative engagement with the floating mandrel.

FIG. 31 is an elevational view of the carriage.

FIG. 32 is a view, in end elevation of the construction shown in FIG. 31, certain parts being shown in section, illustrating the carriage jaws in operative position with respect to the floating mandrel, the positions of the parts here corresponding to the positions of the parts shown in FIG. 29.

FIG. 33 is a view, similar to FIG. 32, and shows the positions of the respective parts when the carriage jaws are moved upwardly out of operative engagement with the floating mandrel, the positions of the parts here corresponding to the positions of the parts shown in FIG. 30.

FIG. 34 is an elevational view of the right end of the turret and shows a portion of the mechanism employed for moving the clamp jaws into and out of operative position with respect to the floating mandrel.

FIG. 35 is a view, in end elevation, of the construction shown in FIG. 34, the clamp jaw being shown in operative position.

FIG. 36 is a top plan view of one of the clamp jaws shown in FIG. 35 and certain of the associated operating mechanism.

FIG. 37 is a horizontal sectional view taken along the line 37-37 of FIG. 38 and showing, at an enlarged scale, the manner in which the clamp jaws cooperate with the floating mandrel and how one of the receiving mandrels cooperates with the floating mandrel to hold it against endwise and rotary movement.

FIG. 38 is a vertical sectional view taken along the line 38-38 of FIG. 37.

FIG. 39 is a horizontal sectional view taken along the line 39-39 of FIG. 37.

FIG. 40 is a view, in side elevation, of the turret.

FIG. 41 is a vertical sectional view taken along the line 41-41 of FIG. 42.

FIG. 42 is a vertical sectional view taken along the line 42-42 of FIG. 40.

FIG. 43 is a vertical sectional view at an enlarged scale taken along the line 43-43 of FIG. 41.

FIG. 44 is a view, partly in elevation and partly in section showing the arrangement of the compressor hydraulic operator and how it cooperates with a compressor-doffer.

FIG. 45 shows the arrangement of the doffer hydraulic operator and how it cooperates with a compressor-doffer.

Referring now particularly to FIGS. 1 and 2 of the drawings, positioned in side-by-side relation, the reference character 1 designates, generally, a stirring machine embodying the present invention. The stirring machine 1 includes a head mechanism, shown generally at 2, and a stirred casing handling machine, shown generally at 3. It will be understood that the head mechanism 2 and the stirred casing handling machine 3 are mounted on a single frame structure, which is not shown in order to

illustrate more clearly the features of construction of the various parts of the stirring machine 1.

The stirring machine 1 is arranged and constructed for automatically stirring a thin walled tubular cellulosic sausage casing 4 of indefinite length as it is unwound from a reel 5. Various lengths of stirred strand are formed by the stirring machine 1. For example, stirred strands can be formed having extended lengths of 55', 80' or 100' as may be desired. These extended lengths of stirred strands are illustrative of typical lengths and it will be understood that greater and lesser lengths can be stirred. The extended lengths can be of the order of 40' to 150', more or less, as may be desired and depending upon the construction of the stirring machine 1. In order to stir these various lengths of casing the stirred casing handling machine 3 is movable endwise with respect to the head mechanism 2. The stirring machine 1 will be described for operation in conjunction with the stirring of 100' lengths of casing and the manner in which suitable adjustment is made for stirring the other lengths of casing will be described.

The reel 5 on which the casing 4 is wound flatwise is mounted for rotation with a shaft 6. Associated with the shaft 6 is an electrically operated brake 7 which is normally energized when the stirring machine 1 is in operation and is deenergized when the stirring machine 1 is stopped, or in particular when the head mechanism 2 is stopped, in order to prevent further unwinding of the casing 4. The flat tubular casing 4 is threaded between a squeeze roll 8 and a measuring roll 9, with the arrangement being such that the casing 4 is unreeled from the reel 5 at a speed of 8' per second, although other speeds can be employed if desired. The squeeze roll 8 can be driven by friction between it and the casing 4 or it can be geared to the measuring roll 9 to rotate synchronously therewith.

The measuring roll 9 is mounted for rotation with a shaft 10 on which an electrically operated brake 11 is provided which, like the brake 7, is arranged to be deenergized when the stirring machine 1 is stopped, or in particular when the head mechanism 2 is stopped, to prevent further rotation of the shaft 10. The shaft 10 is connected through an electrically operated clutch 12 to a sprocket 13 which is driven by a chain 14 from a drive sprocket 15 on a drive shaft 16 which is rotated by a drive motor 17 that preferably is a variable speed motor and is arranged to rotate the shaft 16 at a speed of 320 r.p.m. The motor 17 preferably is a three phase alternating current motor. However, for illustrative purposes it is shown and described herein as a single phase motor to simplify the disclosure.

It is desirable that means be provided for detecting a defect in the casing 4 after it passes between the squeeze roll 8 and the measuring roll 9 and before it is operated upon by the head mechanism 2. For this purpose tear rolls 18-18 are provided above and below the casing immediately to the left of the squeeze roll 8 and measuring roll 9. Normally they are held apart by pressure of the inflated casing to hold the contacts of the tear switch 19 closed. As long as the contacts of the tear switch 19 remain closed, the motor 17 continues to be energized, unless otherwise controlled. However, should a defect in the casing appear causing it to deflate, the tear rolls 18-18 move toward each other and open the contacts of the tear switch 19 and deenergize the drive motor 17.

The casing 4 is directed by vertically extending side guide rolls 20-20, immediately to the left of the tear rolls 18-18, onto the leading end 21 of a horizontal tubular floating mandrel 22. Air under pressure flows through the floating mandrel 22 and out of its leading end 21 for inflating the casing, as indicated at 23, in order to facilitate the stirring operation. Positioned underneath the leading end 21 of the floating mandrel 22 is a support roll 24 having a grooved surface for interengaging with the inflated casing 23 and supporting the

leading end 21 of the floating mandrel 22. The support roll 24 is caused to rotate in the direction indicated by the arrow thereon at a peripheral speed which is equal to the linear speed at which the inflated casing 23 moves onto the floating mandrel 22. For this purpose the support roll 24 is mounted on a shaft 25 for rotation therewith. A sprocket 26 is fast on the shaft 25 and is driven by a chain 27 from a sprocket 28 that is fast on the shaft 10. The chain 27 also extends over a sprocket 29 on a shaft 30 which is employed for driving a stirring head that is indicated, generally, at 31 that can be constructed as disclosed in U.S. Patent No. 2,722,714, issued November 8, 1955.

The stirring head 31 employs upper and lower stirring belts 34-34 which are provided with stirring dogs and are trained over pairs of pinions 35-35 and 36-36 positioned above and below the inflated casing 23 intermediate the ends of the floating mandrel 22 and nearer to the leading end 21 thereof. The stirring belts 34-34 also are trained over pairs of pinions 37-37 and 38-38. The arrangement is such that the stirring belts 34-34 effect the stirring operation on the inflated casing 23 continuously. It will be observed that the lower right pinion 38 is mounted on the shaft 30 for rotation therewith. By this means the lower stirring belt 34 is driven. Fast on the shaft 30 is a gear 39 which drives a gear 40 which is fast on a shaft 41 on which the upper right pinion 38 is mounted. Thus the upper and lower stirring belts 34-34 are driven at the same speed in the directions indicated by the arrows on the several pinions to effect the stirring operation between the pairs of pinions 35-35 at the point 42. The stirred casing is indicated at 43 immediately to the left of the point of stirring 42. While the stirring head 31 has been described as employing the stirring belts 34-34, it will be understood that other stirring means can be employed. For example, instead of using two stirring belts located on opposite sides of the inflated casing 23, three such stirring belts can be employed equally spaced around the inflated casing or 120° apart as shown in U.S. Patent No. 2,722,714, issued November 8, 1955. Also, instead of stirring belts, stirring wheels can be employed which are provided along their outer peripheries with stirring teeth or dogs similar to the stirring teeth or dogs on the stirring belts 34-34. Either two such stirring wheels can be employed on opposite sides of the inflated casing 23, or three such stirring wheels can be used in 120° spaced relationship as shown in U.S. Patent No. 2,983,949, issued May 16, 1961. If desired, four such stirring wheels can be used as shown in U.S. Patent No. 2,819,488, issued January 14, 1958. In such case they are mounted in 90° spaced relationship around the inflated casing 23. Whatever type of stirring head 31 is employed, the arrangement preferably is such that it operates continuously to stir the inflated casing 23 at the stirring point 42 to provide the stirred casing 43 which moves along the floating mandrel 22 at a uniform speed. For the conditions above described the stirred casing 43 moves along the floating mandrel 22 at a speed of 3.2" per second.

With a view to insuring that the stirred casing 43 moves along the floating mandrel 22 at a uniform speed, compaction means in the form of upper and lower compaction rolls 44 and 45 are located above and below the floating mandrel 22 in juxtaposition to the point of stirring 42 and to the left of the stirring head 31. They are formed of soft resilient material and are centrally grooved in order to avoid any damage to the stirred casing 43 as it moves there between. The upper compaction roll 44 may rotate freely or it may be driven with the lower compaction roll 45 which is mounted for rotation with a shaft 46 on which a sprocket 47 is mounted to be driven by a chain 48 from a sprocket 49 on a shaft 50. The arrangement is such that the peripheral speed of the lower compaction roll 45 is equal to or less than the speed

at which the stirred casing 43 moves along the floating mandrel 22.

The shaft 50 is driven from the drive motor 17 in the following manner. The shaft 50 is driven through mitre gears 51-51 from a shaft 52 which extends vertically and has connection through reduction gears 53a, 53b, 53c and 53d with a vertical shaft 54 that is driven by mitre gears 55-55 from a horizontal shaft 56 on which there is an electrically operated brake 57. The arrangement is such that, on deenergization of the drive motor 17 or other control causing the rotation of the shaft 56 to cease, the brake 57 is effective to stop such further rotation and further movement of the parts driven thereby. The shaft 55 is connected by a electrically operated clutch 58 to a sprocket 59 which is driven by a chain 60 from a drive sprocket 61 on the shaft 16. By suitably controlling the energization of the clutch 58, it is possible to stop rotation of the shaft 56 and movement of the parts driven thereby while the motor 17 continues to drive the shaft 16 through the clutch 12. Likewise, it is possible to operate the clutch 12 and prevent further rotation of the shaft 16 and parts driven thereby while permitting the shaft 56 to continue to rotate. In general, it is pointed out that the stirred casing handling machine 3 is driven by the drive motor 17 through the shaft 56 and parts driven thereby and that the head mechanism 2 is driven by the shaft 16 and the elements directly connected thereto. By selectively controlling the energization of the clutches 58 and 12 it is possible selectively to control the operation of the stirred casing handling machine 3 and the head mechanism 2 as may be desired. Ordinarily, however, the operation of the stirring machine 1 is a continuous operation with the clutches 58 and 12 being de-energized or unclutched only under certain special circumstances requiring such action.

The floating mandrel 22, as the name implies, floats between the stirring belts 34-34 with the unshirred inflated casing 23 moving over the leading end 21 and being stirred, in the manner described, against the compaction rolls 44-45. The floating mandrel 22 is held in this position at its trailing end 63 by clamp means, indicated generally at 64. The clamp means 64 not only holds the floating mandrel 22 against endwise and sidewise movement, but also it holds it against rotation about its longitudinal axis. However, since the casing is stirred, as indicated at 43, onto the floating mandrel 22, it is necessary to provide means for unclamping the clamp means 64 in order to permit the transfer of the stirred casing from the floating mandrel 22. At the same time, it is necessary to hold the floating mandrel 22 against endwise and side wise movement as well as against rotary movement. The manner in which this is accomplished will be described presently.

The clamp means 64 includes clamp members 65-65 which are arranged to engage the trailing end 63 of the floating mandrel 22 from opposite sides and to hold it not only against endwise and sidewise movement but also against rotation about its longitudinal axis. The clamp members 65-65 are pivoted at their ends at 66-66 on the upwardly extending arms of bell cranks 67-67 which are pivoted at 68-68 about fixed axes.

In order to supply air under pressure to the tubular floating mandrel 22 for inflating the casing at 23 at the leading end 21, an air connection 69 is provided in one of the clamp members 65. The air connection 69 is provided with a valve arrangement which prevents the escape of the compressed air when the clamp members 65-65 are disengaged from the trailing end 63 of the floating mandrel 22. As will be described hereinafter, air under pressure continues to flow through the floating mandrel 22 for maintaining the casing inflated at 23 after the clamp members 65-65 are moved out of engagement with the trailing end 63 of the floating mandrel 22.

The other arms of the bell cranks 67-67 are pivotally connected at 70-70 to the upper ends of operating rods

71—71 which are commonly pivoted at 72 to the outer end of a clamp operating lever 73 which is pivoted at 74 about a fixed axis. Intermediate the ends of the clamp operating lever 73 is a follower roll 75 which interfits with a cam groove 76 in a box type mandrel clamp cam 77 which is fast on a horizontal cam shaft 78.

It has been pointed out hereinbefore that the shirred casing handling machine 3 is movable relative to the head mechanism 2 in order to accomodate different lengths of shirred strands of casing. Also, it has been pointed out that the shirring machine 1 is shown in the position for shirring 100' lengths of casing. In this position the shirred casing handling machine 3 is located furthest away from the head mechanism 2. In order to accomodate this shifting of the shirred casing handling machine 3, the cam shaft 78 has a splined connection 79 with a cam shaft 80 that is arranged to be rotated at a speed of one revolution in each twelve and one-half seconds for the handling of 100' shirred strands. Provision is made for increasing this speed to accommodate shorter lengths of shirred strands. In effect, then, the cam shaft 78 and the cam shaft 80 can be considered as a single shaft with the splined connection 79 therebetween.

Fast on the cam shaft 80 is a worm wheel 81 which is driven by a worm 82 on a vertical shaft 83. Slidable on the vertical shaft 83 are gears 84a, 84b and 84c that are arranged to be moved axially of the vertical shaft 83 by a gear shifter yoke 85. The gear shifter yoke 85 includes a rack 86 with which a pinion 87 has driving engagement and is mounted on a shaft 88 for rotation by a crank 89. The gear shifter yoke 85 occupies a position corresponding to the lowest speed of the cam shaft 80. Accordingly, the crank 89 is shown by full lines. It is shown by broken lines in two other positions which correspond, respectively, to the two higher operating speeds for the cam shaft 80. Fast on the vertical shaft 54, which it will be recalled is driven by the motor 17, are gears 90a, 90b and 90c. It will be noted that the gear 90a has driving connection with the gear 84a and that the gears 90b and 90c are out of engagement. On movement of the gear shifter yoke 85 by rotation of the crank 89 to the intermediate position, the gear 84a is moved out of engagement with the gear 90a and gear 84b is moved into driving engagement with gear 90b. Likewise, when the crank 89 is moved to the lowermost position shown by the broken lines, the gear 84b is moved out of driving engagement with the gear 90b and the gear 84c is moved into driving engagement with the gear 90c.

After a predetermined length of the shirred casing 43 has moved past the compaction rolls 44—45, it is desirable that this length be severed from the following shirred casing to permit the shirred strand, thus severed, to be moved off of the floating mandrel 22 for subsequent treatment in a manner to be described. For this purpose shirred casing severing means, or a severing machine shown generally at 93, is employed. It includes a housing 94 that is stationarily mounting on the frame of the shirring machine 1 between the shirring head 31 and the shirred casing handling machine 3. In order to provide a separation between the length of shirred strand to be severed from the following shirred casing a holding finger or digger 95 is movably mounted on the housing 94 and, at the appropriate time, is arranged to move upwardly about $\frac{3}{8}$ " in order to separate the adjacent folds and pleats of the shirred casing 43. The arrangement is such that the holding finger or digger 95 not only is moved upwardly to engage and separate the shirred casing 43 adjacent the compaction rolls 44—45 but also it moves along the floating mandrel 22 at the speed at which the shirred casing 43 moves therealong.

In order to facilitate the severance of the shirred strand from the preceding shirred casing 43, pinch rolls 96—96 are mounted on pinch roll brackets 97—97. The pinch rolls 96—96 are rotated in the directions indicated by the arrows associated therewith for refolding the folds

and pleats of that portion of the casing which is extended from the holding finger or digger 95. The arrangement is such that the pinch rolls 96—96 move along the floating mandrel 22 at a speed which is greater than the speed at which the casing 43 is shirred. The pinch rolls 96—96 are formed of soft material of a frictional character and are moved toward each other to pinch the shirred casing therebetween against the floating mandrel 22. Since the pinch rolls 96—96 move along the floating mandrel 22 at a speed in excess of the speed at which the holding finger or digger 95 moves therealong, the intervening portion of the casing is unfolded. At the same time, the pinch rolls 96—96 are rotated in the directions indicated at a peripheral speed which is several times the speed at which the shirred casing 43 moves along the floating mandrel 22 for the purpose, as stated, of refolding the unfolded casing after it has been severed from the following shirred casing. The pinch rolls 96—96 are mounted on pinch roll brackets 97—97 which, in turn are mounted on horizontal shafts 98—98 carried by the housing 94. The arrangement is such that, when the severing operation is to be performed, the pinch roll brackets 97—97, which normally are spaced away from the floating mandrel 22, are rotated toward each other to bring the pinch rolls 96—96 into the engagement previously described with the shirred casing and at the same time the pinch rolls 96—96 are rotated.

After the holding finger or digger 95 is moved into engagement with the shirred casing 43 in the manner described and the portion of the casing to the left is extended through the operation of the pinch rolls 96—96, a scoring yoke or cutter 99 is moved upwardly about $2\frac{3}{8}$ " to engage tightly the opposite sides of the floating mandrel 22 with the extended portion of the casing therebetween. The scoring yoke or cutter 99 is of bifurcated construction with the arms being formed by relatively stiff round wires or like rigid members which have substantially point contact engagement with opposite sides of the mandrel 22 and serve to score the casing. This starts the casing to tear and to be severed on opposite sides of the floating mandrel 22. Since the pinch rolls 96—96 are moved along the floating mandrel 22 at such a speed as to apply an endwise tension to that portion of the casing between them and the holding finger or digger 95, the tension thus applied is sufficient to complete the severance of the casing which is started by the scoring operation in the manner described. Provision is made also for moving the scoring yoke or cutter 99 along the floating mandrel 22 at the same speed that the holding finger or digger 95 moves therealong. The movement of the holding finger or digger 95 and of the scoring yoke or cutter 99 along the floating mandrel 22 is the order of $2\frac{3}{8}$ " after which they are moved downwardly through an extent equal to the extent that they were moved upwardly as described. Thereafter, the pinch rolls 96—96, after having completed their refolding operations on the portion of the casing that was extended to permit the severing operation, are moved laterally away from the floating mandrel 22 by a corresponding outward movement of the pinch roll brackets 97—97.

The shirred casing severing means 93 is operated periodically by a shaft 100 which is driven by a one revolution clutch 101 at a speed of 30 r.p.m. The clutch 101 is mounted on the shaft 50, previously described, and is driven thereby. The one revolution clutch 101 is prevented from rotating by a shoulder 102 that extends radially therefrom for engagement by a detent 103 which is pivoted at 104 about a fixed axis on the housing 94. A spring 105 normally holds the detent 103 in position to engage the shoulder 102. The spring 105 is connected to a link 106 which is connected at 107 to the detent 103. The left end of the link 106 is pivoted at 108 to the upper end of an arm 109 which is fast on a horizontal shaft 110 which has a cam arm 111 fast thereon. At its lower end the cam arm 111 carries a roll 112 which is

arranged to be engaged by a cam surface 113 on a trip cam 114 that is fast on the cam shaft 89. It will be understood that the periodicity of operation of the shirred casing severing means or the severing machine 93 is controlled by the speed at which the cam shaft 89 is rotated. This speed is varied, as above described, by changing the position of the gear shifter yoke 85 in accordance with the length of the strand that is to be shirred. The shirred and severed strand is indicated at 115.

Provision is made for compressing the shirred strand 115 against the clamp members 65—65 and subsequently for transferring it from the floating mandrel 22. For this purpose a carriage shown generally at 116 is provided. The carriage 116 is arranged to be reciprocated along the floating mandrel 22 from an initial position adjacent the compaction rolls 44—45 where the shirred strand 115 is severed from the following shirred casing 43 and a terminal position beyond the trailing end 63 of the floating mandrel 22. The carriage 116 is mounted for such reciprocatory movement by horizontally extending upper and lower support rails 117—118 which are mounted at their left ends as cantilevers. Also, the support rails 117—118 are rotatable about their longitudinal axes to effect certain control operations of carriage jaws 119—119 which are mounted on the carriage 116. The carriage jaws 119—119 have semi-circular ends 120—120 that are arranged to surround the floating mandrel 22 at a position adjacent the compaction rolls 44—45 after the casing has been severed in the manner above described. However, the arrangement is such that the semi-circular ends 120—120 have substantial clearance with the floating mandrel 22 and their left sides are arranged to engage the right end of the severed shirred strand 115 so that, on movement of the carriage 116 to the left, the shirred strand 115 is correspondingly moved along the floating mandrel 22. The carriage jaws 119—119 are pivoted at 121 on an arm 122 which extends from and is rotatable with the lower rail 118. The carriage jaws 119—119 have a scissors like movement with respect to the floating mandrel 22 and with respect to a receiving mandrel aligned therewith as described hereinafter. The upper ends of the carriage jaws 119—119 are pivoted at 123—123 to links 124—124 which, in turn, are pivoted on a transverse pin 125 which extends at its ends through slots having vertical lower slot portions 127—127 and upper arcuate slot portions 128—128 in carriage plates 129—129 between which the carriage jaws 119—119 and the links 124 are mounted. Carriage bearings 130—130 are provided for mounting the carriage 116 for movement along the upper and lower support rails 117—118. The arrangement for operating the carriage jaws 119—119 is such as to cause them to move toward opposite sides of the floating mandrel 22 for engaging the shirred strand 115 after it has been severed. In addition, the positions of the carriage jaws 119—119 are controlled to move them upwardly out of registry with the clamp members 65—65 after these clamp members are closed with the carriage 116 in the position shown in FIG. 1 and thereafter it is moved from this terminal position back to the initial position along the support rails 117—118.

The operation of the carriage jaws 119—119 with respect to the carriage 116 is effected by rotating the support rails 117—118 about their longitudinal axes. This is accomplished by selectively rotating upper and lower operating arms 131—132 which are keyed, respectively, to the upper and lower support rails 117—118. Pivoted to the upper operating arm 131 at 133 is a link 134 having a slot 135 at its lower end which provides a lost motion connection to the lower operating arm 132. Provision is made for biasing the operating arms 131 and 132 toward each other by means of a coil tension spring. Pivoted connected at 136 to the link 134 is the upper end of an operating rod 137 the lower end of which is pivoted at 138 to a carriage clamp operating lever 139 which is pivoted at 140 about a stationary axis. A fol-

lower roll 141 is carried by the carriage clamp operating lever 139 intermediate its ends and it projects into a cam groove 142 in a box type carriage jaw operating cam 143 which is fast on the cam shaft 78. The shape of the cam groove 142 and the speed at which the carriage jaw operating cam 143 rotates are such as to effect the proper operation of the carriage jaws 119—119 to permit movement of the carriage 116 from the terminal position shown in FIG. 1 past the clamp members 65—65 to the initial position adjacent the compaction rolls 44—45 and also to move the semi-circular ends 120—120 into operative position on opposite sides of the floating mandrel 22 for engaging the severed end of the shirred strand 115.

For moving the carriage 116 in the reciprocatory manner previously referred to, a chain 146 is provided. The chain 146 is connected at 147 to the carriage 116 so that tension applied in one direction or the other causes it to move in the corresponding direction. The chain 146 is trained over sprockets 148—148 which are mounted, respectively, on shafts 149—149 that are arranged to move with the shirred casing handling machine 3 when it is adjusted to accommodate a different length of shirred strand 115. In addition, the chain 146 is trained over a sprocket 150 that is mounted on a shaft 151, the axis of which is fixed with respect to the head mechanism 2. Thus the shaft 151 and sprocket 150 mounted thereon remain stationary when the shafts 149—149 and sprockets 148—148 mounted thereon are moved in the manner described for adjusting purposes. The chain 146 is driven in one direction or the other by a sprocket 152 which is fast on a vertical shaft 153 the axis of rotation of which is positioned to the right of the compaction rolls 44—45 in order to permit the travel of the carriage 116 to the initial position. The vertical shaft 153 is driven through a train of gears comprising gears 154a, 154b, 154c, and 154d by a vertical shaft 155 on which gears 156a, 156b, and 156c are mounted to be shifted by the gear shifter yoke 85 for selective engagement with gears 157a, 157b, and 157c that are fast on a vertical shaft 158. The gears 154b and 154c are mounted for rotation with a vertical shaft 154e. Recalling that the shirring machine 1 is shown in the position for shirring 100' lengths of casing, the gear shifter yoke 85 is in a corresponding position so that the gear 156a is in driving engagement with the gear 157a on the shaft 153 and the latter rotates at a corresponding speed. When the gear shifter yoke 85 is moved to the intermediate position, the gear 156a is moved out of engagement with the gear 157a and the gear 156b is moved into driving engagement with the gear 157b. Likewise, when the shifter yoke 85 is moved to the third position, the gear 156b is moved out of driving engagement with the gear 157b and the gear 156c is moved into driving engagement with the gear 157c. Also mounted on the vertical shaft 158 is a gear 159 which is in driving engagement with a gear 160 that is fast on the upper end of a vertical shaft 161 at the lower end of which there is fast a sprocket 162. Trained over the sprocket 162 is a chain 163. Secured to the chain 163 is a block 164 from which a follower roll 165 depends for engagement with a cam groove 166 in a barrel type carriage reciprocating cam 167 that is fast on the cam shaft 89. The chain 163 is also trained over a sprocket 168 on a shaft 169. As the cam shaft 89 is rotated in the manner described, the carriage reciprocating cam 167 is correspondingly rotated and the follower roll 165 moves along the cam groove 166. The arrangement is such that the follower roll 165 and the chain 163 are moved, first in one direction and then in the other, to effect a corresponding rotation of the sprocket 162 in one direction or the other and a corresponding movement of the carriage 116 along the support rails 117—118 in one direction or the other.

When the carriage 116 moves from right to left with the carriage jaws 119—119 having their semi-circular ends 120—120 in engagement with the severed end of

the shirred strand 115, the strand 115 is moved to the left along the floating mandrel 22 and its left end engages and is stopped by the clamp members 65—65 while the right end continues to be moved as the carriage 116 continues to move in this direction. The shirred strand 115 then is compressed against the clamp members 65—65. Since substantial force is required to compress the shirred strand 115 in this manner and because of the manner in which the carriage 116 is moved in the compressing direction by the chain 146 from the carriage reciprocating cam 167 through the intervening mechanical connections, it is desirable that additional force be made available for moving the carriage 116 while it is compressing the shirred strand 115. For this purpose a bracket 170 is mounted on the carriage 116 and a connecting rod 171 is interconnects it with a single acting air operator that is indicated, generally, at 172. The air operator 172 is controlled by a three way solenoid valve 173. A solenoid 174 controls the operation of a valve 173 in proper timed relation with the operation of the cam shaft 80. The operation of the air operator 172 is such that, as the carriage 116 is moved to the left and the shirred strand 115 is compressed against the clamp members 65—65, air pressure is applied to the air operator 172 to assist the movement of the carriage 116 in this direction for completing the compressing operation against the clamp members 65—65, and, after they are opened, assisting in moving the carriage 116 to transfer the shirred and compressed strand 115 from the floating mandrel 22. Thereafter the solenoid valve 173 is operated to exhaust the compressed air to the atmosphere for free retraction of the connecting rod 171 to its initial position.

With a view to handling the shirred strand 115 after it is transferred from the floating mandrel 22 for subsequent further compression thereof, a turret, shown generally at 177, is provided. The turret 177 is rotatable about a horizontal axis which is parallel to the longitudinal axis of the floating mandrel 22. The turret 177 includes receiving mandrel holders 178 which are illustrated as being six in number. The receiving mandrel holders 178 are uniformly circumferentially spaced about the axis of rotation of the turret 177 and also mounted for individual endwise movement through a slight extent relative to the turret 177 itself. Mitre gears 179—179 are employed to drive the turret 177 and they connect it with an inclined shaft 180 which has a circular plate 181 at its lower end from which follower rolls 182 depend for engagement with and disengagement from a cam groove 183 that extends around a barrel type turret index cam 184 that is fast on the cam shaft 78. The arrangement of the follower rolls 182 and the cam groove 183 is such that the inclined shaft 180, and thereby the turret 177, is indexed through twelve steps for a complete rotation of the turret 177. The follower rolls 182 one by one successively engage and disengage the cam groove 183 for each revolution of the index cam 184 to rotate the shaft 180 and thereby the turret 177 through 30° for each revolution of the index cam 34.

Extending forwardly from each of the receiving mandrel holders 178 is a horizontal tubular longitudinally apertured receiving mandrel 187. There are six receiving mandrel holders 178 and six receiving mandrels 187. They are arranged, on indexing of the turret 177, to be moved, one by one, into endwise alignment with the floating mandrel 22 for receiving therefrom the shirred strand 115. With a view to moving the receiving mandrel 187 that is in alignment with the floating mandrel 22 into endwise engagement therewith for supporting it against endwise, sidewise and rotary movement, a receiving mandrel shifter arm 188 is provided that is arranged to operatively engage, one by one, the receiving mandrel holders 178 as the turret 177 is indexed. It will be understood that the receiving mandrel shifter arm 188 is operatively connected to the receiving mandrel holder 178 carrying the receiving mandrel 187 that is in alignment with the

floating mandrel 22 and that this operative engagement takes place when the turret 177 is indexed to this position. The receiving mandrel shifter arm 188 is fast on the upper end of a vertical shaft 189 which has a radially extending arm 190 at the lower end that carries a follower roll 191 which extends into a cam groove 192 in a receiving mandrel shifter cam 193 that is fast on the cam shaft 78. The arrangement and construction of the receiving mandrel shifter cam 193 and associated parts are such as to effect a relatively slight endwise movement of each receiving mandrel holder 178 and the receiving mandrel 187 carried thereby into endwise engagement with the floating mandrel 22 when in alignment therewith. This endwise movement may be of the order of $\frac{1}{16}$ ".

It was pointed out hereinbefore that air is supplied under pressure to the air connection 69 in one of the clamp members 65 for inflating the casing as indicated at 23. When the clamp members 65 are disengaged from the trailing end 63 of the floating mandrel 22, it is desirable that the flow of air under pressure be continued. This is accomplished by supplying air under pressure through the longitudinal aperture in the particular receiving mandrel 187 that is in endwise supporting engagement with the floating mandrel 22. The arrangement for accomplishing this continued supply of air under pressure is shown diagrammatically in FIG. 4 of the drawings. Here it will be observed that each of the receiving mandrel holders 178 is movable with respect to a part 194 of an air manifold 195 which is circular in construction but is shown in developed form in FIG. 4 for illustrative purposes. An air passageway 196 extends through the air manifold 195 and through the several parts 194, as shown, for connection to an air passageway 197 in each of the receiving mandrel holders 178 when they are moved forwardly, one by one, as shown uppermost in FIG. 4, to move the respective receiving mandrel 187 into endwise supporting engagement with the floating mandrel 22 at its trailing end 63. When a mandrel holder 178 is thus moved forwardly, the air passageway 197 therein is in communication with the air passageway 196 in the respective part 194 and air under pressure then can be supplied from an air supply, indicated at 198, through the respective tubular receiving mandrel 187 into the tubular floating mandrel 22 to maintain the inflated condition of the casing at the leading end 21 in the manner previously described. When the receiving mandrel holders 178 are in the retracted positions, as shown in FIG. 4, for the other mandrel holders, the connections to the air passageway 196 in the respective parts 194 of the air manifold 195 are closed off and thus the compressed air is not permitted to escape.

It is desirable that the shirred strand 115, after it has been transferred onto one of the receiving mandrels 187, be recompressed and that it be held under compression for a predetermined time which is the time that is required to rotate the turret 177 substantially through a complete revolution. For this purpose a compressor-doffer 199 is slidably mounted on each of the receiving mandrels 187. The compressor-doffer 199 on the receiving mandrel 187 which is in alignment with the floating mandrel 22, as shown in the uppermost part of FIG. 4, is limited in its movement to the left by a stop 200. When the shirred strand 115 is shifted by the carriage 116 onto the receiving mandrel 187 in this position, it picks up the compressor-doffer 199 on this particular receiving mandrel 187 and moves it against the stop 200.

As soon as the turret 177 has been indexed to the next step following the position where the shirred strand 115 was transferred to the receiving mandrel 187 in alignment therewith, it is desirable that it be recompressed as noted. For this purpose, as shown in FIG. 4, a compressor member 201 is employed which has a compressor surface 202 against which the shirred strand 115 can be endwise compressed by moving the compressor-doffer

199 on the next receiving mandrel 187 toward the compressor member 201. In order to accomplish this compressing action, compressor means, shown generally at 203 in FIG. 1, is employed. The compressor means 203 includes a pusher 204 that is mounted at the forward end of a connecting rod 205 which extends from a compressor hydraulic operator 206. A solenoid valve 207, having a solenoid 208, is employed for controlling the energization of the compressor hydraulic operator 206 to move the pusher 204 either forwardly or rearwardly on the application of suitable hydraulic pressure. Provision is made, as the turret 177 is indexed, for connecting the pusher 204 operatively to the compressor-doffers 199, one by one, and then the solenoid valve 207 is operated by energization of the solenoid 208 to operate the compressor hydraulic operator 206 for moving the next compressor-doffer 199 toward the compressor member 201 and away from the stop 209. The movement of the compressor-doffer 199 is sufficient to move its left end past a holding member 209, FIG. 4, which is provided with a holding surface 210 that is in parallel spaced relation to the compressor surface 202 on the compressor member 201. As the turret 177 is subsequently indexed, the compressor-doffers 199, one by one, are moved from the pusher 204 in the extended position to engage the holding surface 210. Thus, as the turret 177 is subsequently indexed, the compressor-doffers 199 bear against the holding surface 210 while the stirred strands bear against the compressor surface 202 and thus they are held under compression on the respective receiving mandrel 187 during subsequent indexing of the turret 177.

After the turret 177 has completed nearly a full revolution and a receiving mandrel 187 has been moved beyond the edges of the compressor surface 202 and the holding surface 210, it is desired that the completed strand be doffed from this particular receiving mandrel 187. For this purpose doffer-means, shown generally at 212 in FIG. 1, is employed. The doffer-means 212 includes a doffer yoke 213 that is arranged to engage the compressor-doffers 199, one by one, as they are moved into the doffing position on indexing of the turret 177. The doffer yoke 213 is mounted at the outer end of a connecting rod 214 which extends from a doffer hydraulic operator, shown generally at 215. The doffer hydraulic operator 215 is controlled by a solenoid valve 216 which has a solenoid 217 that is arranged to be energized at the proper time for effecting the desired operation of the doffer hydraulic operator 215.

The electrical circuits that can be employed for effecting the energization of certain of the electrical devices previously described in proper timed relationship are shown at the lower right side of FIG. 2. Here it will be observed that conductors 218-218 are provided which can be connected to a suitable source, such as a 115 volt, 60 cycle alternating current source. These conductors are connected by switches 219-219 to conductors 220-220. On closure of the switches 219-219 the conductors 220-220 are energized and, if the contacts of the tear rolls 18-18 by the inflated casing 23, the motor 17 is energized and it operates to perform the drive functions previously described on the assumption that the clutches 12 and 53 are engaged.

It will be noted that the solenoids 174, 208, and 217 are connected between the conductors 220-220 for energization through contacts 221a, 222a, and 223a, respectively. Provision is made for energizing these solenoids by closing these contacts in the desired timed relationship through cams 221, 222, and 223, respectively, which are mounted for rotation with an auxiliary cam shaft 227. The auxiliary cam shaft 227 can be driven from the cam shaft 89 through the agency of a sprocket 228 on the auxiliary cam shaft 227 connected by a chain 229 to a sprocket 230 on the cam shaft 89.

In operation, assuming that the conductors 218-218

are properly energized, the switches 219-219 are closed and the drive motor 17 is energized to operate the head mechanism 2 and the stirred casing handling machine 3 together with the stirred casing severing means or severing machine 93, in the manner generally described hereinbefore. As pointed out, the stirring head 31 is driven continuously to effect a stirring action on the inflated casing 23 between the upper and lower stirring belts 34-34 at the stirring point 42 against the compaction rolls 44-45. The casing then is stirred, as indicated at 43, on the floating mandrel 22.

As illustrated in FIG. 3 of the drawings, after the stirred strand 115 has been separated by operation of the severing means or the severing machine 93, the carriage jaws 119 are closed around the floating mandrel 22 adjacent the severed end of the stirred strand 115, as shown in step A, and they are then moved to the left on corresponding movement of the carriage 116. The stirred strand 115 is compressed against the clamp members 65-65. This is illustrated as step B where the stirred strand, compressed on the floating mandrel 22, is indicated at 233, it being understood that this is the same strand 115 which is shown in step A as being uncompresed on the floating mandrel 22. Next, the clamp cam 77 operates to move the clamp members 65-65 out of clamping engagement with the trailing end 63 of the floating mandrel 22 after a receiving mandrel 187 has assumed the functions of the clamp members 65-65 in supporting the floating mandrel 22 against endwise, side-wise and rotary movement. This action of the receiving mandrel 187 was initiated in step A, continued in step B and maintained in step C where, with the clamp members 65-65 opened, they permit the compressed strand 233 to be transferred past the clamp members 65-65 by continued movement of the carriage jaws 119 to the position shown in step D. When the transfer of the stirred strand 233 takes place in step C, the compressor-doffer 199 on the receiving mandrel 187 is picked up and, as shown for step D, it is moved against the stop 209 where further movement is prevented. In the meantime, the clamp members 65-65 have reclosed as indicated in step D. Thus, when the carriage 116 is returned to the initial position, the carriage jaws 119 not only are disengaged from the opposite sides of the respective receiving mandrel 187, but also they are bodily moved upwardly to clear the closed clamp members 65-65 as the carriage 116 is moved back to its initial position along the support rails 117-118. In position E the compressor-doffer 199 has been moved forwardly toward the compressor surface 202 on the compressor member 201 by engagement by the pusher 204 and operation of the compressor hydraulic operator 206. The compressed strand is indicated at 234. After the compressed strand 234 has been held, as described hereinbefore and illustrated in FIG. 4, in the compressed position with one end against the compressor surface 202 and the other against the respective compressor-doffer 199, which is held against the holding surface 210 of the holding member 209, the completed strand 235 is doffed as indicated by position F in FIG. 3 on engagement of the doffer yoke 213 with the respective compressor-doffer 199 in the doffing position. Here the compressor-doffer 199 is moved slightly past the right end of the respective receiving mandrel 187 to doff the completed strand 235.

It will be recalled that one of the clamp members 65 is provided with an air connection 69 which is shown in FIG. 1 of the drawings. This air connection 69 is shown in FIG. 4 as being connected to an air supply at 237 which may be the same as the air supply 193 connected to the air manifold 195. Combined with the compressed air that is supplied at 193 and 237 is a lubricant, such as mineral oil or other relatively inert material. The lubricant is atomized and mixed with the air before it is fed at 193 and 237 to flow out of the leading end 21

of the floating mandrel 22 and then over the external surface thereof to leak out under the stirred casing 43 after it has been severed. This provides a thin film over the surface of the floating mandrel 22 and facilitates sliding of the stirred casing therealong.

The twelve positions to which the turret 177 is indexed are shown in FIG. 4. By full lines the positions of the compressor-doffers 199 are shown where one of the receiving mandrels 187 is aligned with the floating mandrel 22. The broken line showing of the compressor-doffers 199 indicates the intermediate position of the turret 177. This position is employed to transfer the next compressor-doffer 199 from the pusher 264 onto the holding surface 219 of the holding member 209.

Where data are specified herein with respect to speed, distance, voltage and the like, it will be understood that the purpose of such references is to illustrate possible values that can be employed, it being understood that other values can be used as and where desired.

As pointed out hereinbefore the unshirred casing 4 is unwound from a reel 5 and is fed to the stirring head 31 to be stirred onto the floating mandrel 22 where splices appear at random locations along the unshirred casing 4. A typical arrangement of a splice is illustrated in FIG. 5 where it will be observed that the ends 240—240 of the unshirred casing 4 are arranged in abutting relation and are secured in this relation by a short length of splicing tape 241. The splice is indicated, generally, at 242 and, as pointed out, occurs at random locations along the casing 4. It is desirable to minimize the amount of stirred casing that appears in a strand immediately following a splice 242. Also it is desirable to avoid engagement of the scoring yoke or cutter 99 with the splicing tape 241. In order to take care of these two conditions, provision is made, as will appear hereinafter, for operating the stirring head 31 and the stirred casing severing means or the severing machine 93 to cause the severing operation, performed by the scoring yoke or cutter 99, to occur immediately after the splice 242 has moved past the locus of severing or past the scoring yoke or cutter 99 along the floating mandrel 22. When these devices are operated in this manner, there is a minimum of length of stirred casing immediately following the splice 242. Stated differently, the operations of the stirring head 31 and of the severing machine 93 are such as to position the splice 242 substantially at the end of a stirred strand the length of which may be either the same as or slightly more than the usual length of a stirred strand or substantially less depending upon the operating conditions.

In order to detect the presence of the splice 242 in the unshirred casing 4 as it is unwound from the reel 5, the apparatus shown in FIGS. 6, 7, and 8 is provided. Upwardly extending support members 243 are employed. Two of them are used and they are mounted in spaced relation at opposite ends of the squeeze roll 8 and measuring roll 9 on a frame of the general type shown in U.S. Patent No. 2,722,714, issued November 8, 1955. Only one of the support members 243 is shown in FIGS. 6, 7 and 8 of the drawings but it will be understood that another like support member is provided and that these support members carry bearings one of which is indicated at 244 for supporting the ends of the shaft 10 on which the measuring roll 9 is mounted. It will be recalled that the shaft 10 is driven through the clutch 12 by the drive motor 17.

The squeeze roll 8 is mounted for rotation on bearings 245, one of which is shown, to rotate about a horizontal axis 246, FIG. 8, of a shaft 247 which is provided with eccentric shaft extensions one of which is shown at 248 where the arrangement is such that the squeeze roll 8 and the shaft 247 can rotate about an axis 249 of the eccentric shaft extension 248 for the purpose of lifting the squeeze roll 8 upwardly away from the measuring roll 9. Each shaft extension 248 is jour-

naled in bearings 250, one of which is shown, that are secured to the respective support member 243 by welding as indicated. A handle 251, FIG. 6 is secured to the eccentric shaft extension 248 at the opposite end of the squeeze roll 8 from that shown in FIG. 6 for the purpose of manually rotating the shaft extensions 248 and thereby raising the squeeze roll 8 out of engagement with the measuring roll 9.

In operation of the stirring machine 1, the squeeze roll 8 and the measuring roll 9 rotate in the directions indicated by the arrows appearing thereon in FIG. 6, where the uninflated casing 4 moving therebetween is illustrated. In the event that a splice as indicated at 242 should appear, because it provides a substantially extra thickness as seen in FIG. 5 between the squeeze roll 8 and the measuring roll 9, the former would be lifted upwardly to an extent depending upon the additional thickness as a result of the presence of the splicing tape 241. Advantage is taken of this upward displacement of the squeeze roll 8 to detect the presence of the splice 242 and to utilize the change in position of the squeeze roll 8 and more particularly the rotation of the shaft 247 about the axis 249 of the shaft extensions 248 to provide a signal which is employed for controlling the operation of the stirring head 31 or of the stirred casing severing means or severing machine 93, selectively, as the case may be.

It will be observed that a collar 252 is provided on the projecting end of the shaft extension 248 and is secured thereto by a transverse pin 253. A plate 254 is welded to the collar 252 and it has welded thereto an upwardly and outwardly extending arm 255 that is arranged to engage a roller 256 at the outer end of a plunger 257 which operates contacts 258a of a splice detecting switch that is shown generally at 258. The contacts 258a are referred to herein as splice detecting contacts and they are closed on the occurrence of a splice 242 between the squeeze roll 8 and the measuring roll 9. The splice detecting switch 258 includes a suitable housing that is mounted on a bracket 259 which is carried by the upper end of the support member 243. The arrangement is such that, on the occurrence of the splice 242 between the squeeze roll 8 and the measuring roll 9, the former is lifted to an extent depending upon the additional thickness provided by the splicing tape 241. This results in a slight rotation of the shaft extensions 248 about the axis 249 and a corresponding counter clockwise movement of the arm 255, as viewed in FIG. 6, to engage the roller 256 and depress the plunger 257 with the result that splice detecting contacts 258a close momentarily and then open as soon as the splice 242 has moved past the squeeze roll 8 and the measuring roll 9.

It will be understood that other splice detecting means can be employed instead of the mechanical arrangement just described.

FIG. 6 shows additional features of construction of the stirring machine 1. It will be observed that a ball bearing 263 is provided on which the lower tear roll 13 is mounted for rotation about a horizontal stationary axis 264. The upper tear roll 13 is mounted for rotation on a ball bearing 265 about a horizontal vertically movable axis 266 to control the operation of the tear switch contacts 19 for the purpose of opening them in the event that the inflated casing 23 should develop a tear and become deflated. It also will be observed that vertically extending posts 267 have the side guide rolls 20—20 mounted thereon, there being two posts 267 suitably spaced apart on an arm 268 which extends from a transverse plate 269 that forms a part of the frame (not shown) for the stirring machine 1.

Provision is made for closing and opening certain contacts synchronously with respect to the operation of the severing machine 93 which is driven by the motor 17 through the clutch 53 for the purpose of periodically causing the scoring yoke or cutter 99 to engage the

separated folds or pleats of the shirred casing 43 for initiating the severing operation which is completed in the manner described hereinbefore. It will be recalled that the cam shaft 80 rotates in definite timed relation with the operation of the serving machine 93 and that the auxiliary cam shaft 227, driven therefrom by the chain 229, likewise has the same relationship. Accordingly, as shown in FIG. 2, cams 271, 272, 273, 274, and 275 are mounted for rotation with the auxiliary cam shaft 227 and these cams are arranged to control the operation, respectively, of contacts 271a, 272a, 273a, 274a, and 275a. No attempt has been made to show the particular shapes or contours of the cams 271 to 275 or of the cams 224, 225, 226. However, the relationship of these cams to the respective contacts operated thereby, is shown in the chart appearing in FIG. 11 where the operation of the several cams is shown for one complete revolution of the cam shaft 80. It will be observed that cams 271 to 275, by virtue of the driving connections from the drive motor 17, operate synchronously with respect to the periodic operation of the severing machine 93. It follows that the contacts 271a to 275a, likewise operate synchronously with respect to the operation of the severing machine 93.

Referring again to FIG. 2 of the drawings it will be observed that a sprocket 278 is mounted on the shaft 10 for rotation therewith when the clutch 12 is energized to place the motor 17 in driving connection therewith. A chain 279 is trained over the sprocket 278 and also over sprockets 280 and 281 that are arranged to operate, respectively, a head counter, shown generally at 282, and a machine counter, shown generally at 283. The head counter 282 and the machine counter 283 are arranged to measure accurately the number of revolutions of the shaft 10 which in turn are directly related to the number of feet of unshirred casing 4 that pass between the squeeze roll 8 and the measuring roll 9. It will be recalled that the control operations for the stirring head 31 and for the severing machine 93 are carried out in such a fashion as to cause the severing operation to take place after the splice 242 has moved past the locus of severing or past the scoring yoke or cutter 95. Since this location is a substantial distance beyond the squeeze roll 8 and measuring roll 9 in the direction in which the unshirred casing 4 moves and since its movement is at a relatively high speed, it is desirable that accurate measuring means be provided. The head counter 282 and machine counter 283 perform these functions and can be of any suitable type. For example the "Microflex" revolution counter manufactured by Eagle Signal Company of Moline, Illinois can be employed. However, it will be understood that other makes and types of counting equipment can be used. As will appear hereinafter, the head counter 282 and machine counter 283, while constantly driven as long as the shaft 10 is in driving relation with the motor 17, are provided with contacts which are controlled following the detection of a splice 242 and closure of the splice detecting contacts 258a in a manner to be described hereinafter.

Referring now particularly to FIG. 9 of the drawings it will be observed that the relationship between the drive motor 17 and various associated elements is indicated diagrammatically. A brief description of these elements is in order.

On closure of the switches 219—219 to complete the circuit to the energized conductors 218—218, the drive motor 17 is energized provided that the tear switch contacts 19 are closed. These contacts are closed by the separation of the tear rolls 18—18 when the inflated casing 23 continues to be inflated therebetween as seen in FIGS. 2 and 6 of the drawings. It will be recalled that the drive motor 17 rotates the shaft 16 and that it is connected by the machine clutch 58 on energization of machine clutch winding 58w, for placing the shaft 56 in driving relation to the shaft 16. A machine brake 57,

having a machine brake winding 57w, is associated with the shaft 56 for promptly stopping further rotation thereof under certain operating conditions. The shaft 56 is connected through reduction gearing, as indicated schematically in FIG. 9, as comprising the reduction gearing 55 to 81, to rotate the cam shaft 80 or the auxiliary cam shaft 227 for rotating the cams 271 to 275 shown in FIG. 2 and also shown diagrammatically in FIG. 9. These cams are associated, respectively, with contacts 271a to 275a, which are closed and opened once for each revolution of the auxiliary cam shaft 227 or of the cam shaft 80 at and for the times indicated in the chart shown in FIG. 11. It will be observed that contacts 272a and 273a are connected in series and that contacts 274a and 275a are similarly connected. Thus these two sets of contacts function as single sets of contacts. However, it is desirable to use the series arranged contacts in order to be able to adjust independently the cam 273, for example, to control the closure of contacts 273a and also to adjust independently the position of the cam 272 for the purpose of controlling the opening of the contacts 272a. The same relationship is possible with respect to the cams 275 and 274 and their contacts 275a and 274a, respectively, to the end that the overlapping times during which these sets of contacts are closed can be accurately adjusted.

Continuing on with respect to the diagrammatic showing of FIG. 9, it will be recalled that the drive motor 17 also drives through the head clutch 12, having an operating winding 12w, to drive the shaft 10 on which the head brake 11, having a head brake winding 11w, is provided for stopping rotation of the shaft 10 on deenergization of the head clutch 12. Associated with the stirring head 31 is the reel 5 on the shaft 6 on which the reel brake 7 is mounted and which has a reel brake winding 7w that is energized to stop further rotation of the reel 5.

Also driven with the shaft 10, as described hereinbefore, are the head counter 282 and the machine counter 283. The head counter 282 is driven by the continuously rotating sprocket 280 as long as the shaft 10 continues to rotate. The head counter 282 has a head counter clutch winding 282w which is arranged to be energized on the occurrence of certain operating conditions to be described. The head counter 282 is provided with normally closed contacts 282a and normally opened contacts 282b that are arranged to open and close, respectively, when the head counter clutch winding 282w is energized and to close and open, respectively, after a predetermined length, for example, 16', of the unshirred casing 4 has been withdrawn from the reel 5 and moved past the squeeze roll 8. The head counter 282 also is provided with normally open contacts 282c which are arranged to close after energization of the head counter clutch winding 282w only at such a time that a predetermined length for example, 15.33' of unshirred casing 4 has moved past the squeeze roll 8, at which time they close momentarily and then open.

The machine counter 283 is provided with a machine counter clutch winding 283w which is arranged to be energized under certain operating conditions for controlling the operation of the severing machine 93. It also is provided with normally open contacts 283a and 283b which are arranged to close when the machine counter clutch winding 283w is energized and to remain closed until a predetermined length, for example 3', of unshirred casing 4 has moved past the squeeze roll 8, whereupon these contacts open.

FIG. 10 shows, diagrammatically, the circuit connections that can be used for controlling the operation, selectively, of the stirring head 31 and of the severing machine 93. In this circuit diagram certain of the components shown in FIG. 9 are reproduced and in addition relays are illustrated and their circuit connections are shown.

In the event that the unshirred casing 4 were of infinite length and without any splices 242 appearing therealong,

the operation of the shirring machine 1 could be continuous insofar as it being necessary to adjust the operation in accordance with the occurrence of splices. Because of their presence at random locations a control system is provided, as disclosed, herein, whereby the loss incident of these splices 242 is minimized.

In describing the splice control means and its operation it will be assumed that the switches 219—219 are closed and that the motor 17 is energized. It also will be assumed that the machine clutch winding 58w is energized and that the shirred casing handling machine 3 is operating together with the periodic operation of the severing machine 93. It also will be assumed that the head clutch winding 12w is energized and that the head mechanism 2, including the shirring head 31, is continuously operating to form the completed strands 235 of shirred casing in the manner described hereinbefore. Depending upon the time in the period of operation of the severing machine 93 that a splice 242 is detected to operate the splice detecting contacts 258a, the shirring head 31 or the severing machine 93 will be selectively stopped to the end that the splice 242 always will be located in the next shirred strand and that the locus of severing will not coincide with a splice 242. Generally speaking, when the splice 242, if not detected, would appear in the next shirred strand relatively remote from the locus of severing, the shirring head 31 is stopped while the severing machine 93 continues to operate in such a manner as to perform the severing operation after the detected splice 242 has moved slightly past the locus of severing or the location of the scoring yoke or cutter 99. In such case the shirred strand containing the splice may be relatively long or relatively short depending upon operating conditions.

In the event that the splice 242 is detected at a location where it would coincide with the locus of severing of the next shirred strand, the severing machine 93 is stopped while the shirring head 31 continues to operate and shirr the casing to place the splice 242 slightly past the locus of severing after which the operation of the severing machine 93 is restarted to perform the severing operation. In this case a shirred strand containing the splice is provided which is slightly longer than the shirred strand which is formed by the shirring machine 1 in the absence of a splice 242.

In considering the circuit connections shown in FIG. 10 it will be assumed that the switches 219—219 are closed and that the conductors 220—220 are energized. It has previously been pointed out that the conductors 218—218 are energized from a suitable alternating current source. It will be understood that the conductors 220—220 are similarly energized. Also it will be understood that, if it is preferable that the conductors 220—220 be energized from a direct current source, provision can be made for such energization. This can be accomplished by the use of a suitable rectifying means as is understood by those skilled in the art. On closure of the switches 219—219 head clutch relay winding 285w is energized over normally closed contacts 284b of a head relay that is indicated generally at 284 and has normally open contacts 284a and an operating winding 284w. The operating winding 285w forms a part of a head clutch relay, indicated generally at 285, and it has normally closed contacts 285a, normally open contacts 285b and normally closed contacts 285c. As long as the head clutch relay winding 285w remains energized, its contacts 285a and 285c are held open and contacts 285b are held closed to energize head clutch winding 12w in order to maintain the driving connection from the drive motor 17 to the shirring head 31 and thus it is maintained in operation to shirr the casing 23 onto the floating mandrel 22. It also will be observed that normally closed contacts 286a, of a machine relay, shown generally at 286 and having an operating winding 286w, complete a circuit for energizing a machine clutch relay winding 287w of a ma-

chine clutch relay that is indicated, generally, at 287 and has normally closed contacts 287a and normally open contacts at 287b. As long as the machine clutch relay winding 287w remains energized, contacts 287a are held open and contacts 287b are held closed to energize the machine clutch winding 58w and maintain the driving connection between the motor 17 and the shaft 56, thereby maintaining in operation the shirred casing handling machine 3 and in particular maintaining in operation the severing machine 93.

Insofar as the means for controlling the operation of the shirring machine 1 as a result of the occurrence of a splice 242 are concerned, the electrical system as shown in FIG. 10 remains in the condition just described with the head clutch winding 12w energized and the machine clutch winding 58w energized. It will be understood that other controls are provided to permit threading of the shirring machine 1 and to permit jogging of it for adjustment purposes, for testing, etc. Also various safety circuit arrangements can be provided as may be desired to prevent operation of some or all parts of the shirring machine 1 depending upon the requirements.

In describing the operation of the splice control system the circuit connections for which are shown in FIG. 10, it is pointed out that cam controlled contacts 271a are closed for the major portion of each rotation of the cam 271 or of the auxiliary cam shaft 227. The contacts 271a are closed at a time when the splice 242, if undetected, would ultimately appear at a position well past the locus of severing or well past the position of the scoring yoke or cutter 99 when it performs its next severing operation and these contacts continue to be in the closed position until slightly before the performance of the next severing operation. Accordingly, if the splice detecting contacts 258a are closed at a time when the splice 242, if undetected, would appear at a position relatively remote from the locus of severing of the next shirred strand, a circuit would be completed for energizing operating winding 288w of an auxiliary head relay that is shown, generally, at 288 and has normally open contacts 288a and 288b, normally closed contacts 288c which open as a result of time delay approximately .2 of a second after energization of operating winding 288w, normally open contacts 288d and normally closed contacts 288e. The energizing circuit for auxiliary head relay winding 288w is completed through normally closed contacts 289a of a splice at cut relay, shown generally at 289, having normally open contacts 289b and a splice at cut relay winding 289w. It will be understood that the splice detecting contacts 258a close only momentarily. However, this is long enough to complete the energizing circuit for the auxiliary head relay 288w which then seals in through contacts 288a and 288b, now closed, and normally closed contacts 290a of a reset relay, shown generally at 290, having a reset relay winding 290w and additional normally closed contacts 290b. A further result of the energization of auxiliary head relay winding 288w is to close contacts 288d which completes a circuit through time delay contacts 288c for energizing head counter clutch winding 282w. As soon as the head counter clutch winding 282w is energized contacts 282a are opened to prevent energization of reset relay winding 290w and contacts 282b are closed to complete a holding circuit for the head counter clutch winding 282w. Thereafter, time delay contacts 288c are opened but the holding circuit for head counter clutch winding 282w has been established through contacts 282b.

It will be recalled that the splice detecting contacts 258a have been assumed to be closed at such a time that the splice 242, if undetected, would be positioned well past the locus of severing by the scoring yoke or cutter 99. The operation of the shirring head 31 is maintained until this condition is realized since the head counter 282 is operated in accordance with the rotation of the measuring roll 9 or the movement of the unshirred cas-

ing 4 to the stirring head 31. The arrangement of the head counter 282 is such that its contacts 282c are momentarily closed and opened after a predetermined length of the casing 4 has moved past the squeeze roll 8. As a result of the momentary closure of head counter contacts 282c, head relay winding 284w is energized and a holding circuit therefor is established on closure of its contacts 284a through the normally closed contacts 290b of reset relay 290. As a result of the energization of head relay 284w, its normally closed contacts 284b are opened to deenergize the previously indicated energizing circuit for head clutch relay winding 285w. It is deenergized to open contacts 285b for deenergizing head clutch winding 12w to interrupt the driving connection between the motor 17 and the stirring head 31. In addition at contacts 285a an energizing circuit for head brake winding 11w is completed and at contacts 285c an energizing circuit is completed for reel brake winding 7w. Rotation of the shaft 10 and operation of the stirring head 31 are promptly stopped as is further rotation of the reel 5. At this time the splice 242, which had been detected in the manner described, has been positioned just past the locus of severing so that the scoring yoke or cutter 99 will initiate the severing operation just to the right of the splice as it would be viewed in FIG. 2 of the drawings if it were there present. The stirring operation then will continue to be performed since the severing machine 93 and the associated stirred casing handling machine 3 continue to operate.

A short time after the head counter contacts 282c have closed to energize head relay winding 284w, contacts 282a of the head counter 282 are closed to complete part of the circuit for energizing reset relay winding 290w and contacts 282b are opened to open the holding circuit for the head counter clutch winding 282w and permitting it to reset. The reason for initiating the sequence of operations which results in stopping the stirring head 31 in advance of reclosing head counter contacts 282a and reopening head counter contacts 282b is to protect against excessive coast of the stirring head 31 resulting possibly from inadequate braking by the head brake winding 11w which might be injurious to the operation of the head counter 282.

Now it is desired that the stirring head 31 be restarted at a predetermined time in the cycle of operation of the severing machine 93. This is accomplished on closure of contacts 272a and 273a in series under the control of cams 272 and 273 which are driven in synchronism with the operation of the severing machine 93. Since head counter contacts 282a now are closed and, assuming that contacts 272a and 273a are closed in series at the time described, reset relay winding 290w is energized. At contacts 290a the previously traced holding circuit for auxiliary head relay winding 288w is opened and this relay is deenergized with the result that its contacts are opened and closed in the manner described. In addition the holding circuit for head relay winding 284w is opened at contacts 290b and head relay 284 is deenergized. Contacts 284b are reclosed to complete the energizing circuit for head clutch relay winding 285w. The energizing circuits for the head brake winding 11w and reel brake winding 7w are opened and at contacts 285b a circuit is completed for reenergizing the head clutch winding 12w. Thereafter the motor 17 drives through the shaft 10 to operate the stirring head 31 and associated parts.

It has been pointed out that it is undesirable to have the splice 242 appear at the locus of severing by the scoring yoke or cutter 99. The reason for this is that the added thickness provided by the splicing tape 241 would interfere adversely with the performing of the severing operation and might damage the scoring yoke or cutter 99. In the event that the splice 242 is detected at a location along the unshirred casing 4 where, if undetected, it would appear at the locus of severing, it

is desirable to stop the operation of the severing machine 93 and of the associated stirring casing handling machine 3 while permitting the stirring head 31 to continue to operate and shirr the splice 242 past the locus of severing.

Assuming that the splice 242 is detected at a point where it otherwise would appear at the locus of severing, cam operated contacts 271a and series connected cam operated 272a and 273a are opened and for a brief period contacts 274a and 275a are closed in series to effect the energization of splice at cut relay winding 289w. While the energization of this winding 289w occurs each time that a strand is shirred, there is no resulting operation, except when splice detecting contacts 258a are closed during the time that the splice at cut relay winding 289w is energized and its contacts 289b are closed. On closure of splice at cut relay contacts 289b at the time that splice detecting contacts 258a are closed, an energizing circuit is completed for auxiliary machine relay winding 291w of an auxiliary machine relay, shown generally at 291. This relay has normally closed contacts 291a, that are opened with a time delay of the order of .2 second after energization of winding 291w, and normally open contacts 291b. At the time that auxiliary machine relay winding 291w is energized machine counter clutch winding 283w also is energized in parallel therewith and machine counter contacts 283a are closed to complete a holding circuit for windings 291w and 283w so that, after the time delay has expired for contacts 291a, and they open, the energizing circuit for these two windings is maintained through machine counter contacts 283a. A further result of the energization of splice at cut relay 289 is to open normally closed contacts 289a to prevent energization of auxiliary head relay winding 288w. At the time that machine counter clutch winding 283w is energized and machine counter clutch contacts 283a are closed, machine counter contacts 283b also are closed. The machine counter 283 then begins to measure the amount of unshirred casing 4 that moves past the measuring roll 9. Upon closure of machine counter contacts 283b, machine relay winding 286w is energized and its contacts 286a are opened to deenergize machine clutch relay winding 287w. Consequently machine clutch 287 is deenergized and its contacts 287b are opened to deenergize machine clutch winding 58w and its contacts 287a are closed to energize machine brake winding 57w. The driving connection from the motor 17 to the stirred casing handling machine 3 is interrupted and its operation is promptly stopped as a result of the application of the machine brake 57. This involves the stopping of the severing machine 93 and, since the stirring head 31 continues to operate, the casing 43 continues to be shirred until the splice 242 is just past the locus of severing by the scoring yoke or cutter 99. The machine counter 283 determines the length of this interval which is sufficient, as indicated, to permit a length of 3' of unshirred casing to pass the squeeze roll 8 whereupon machine counter contacts 283a and 283b are opened. At contacts 283a the holding circuit for auxiliary machine relay winding 291w and for machine counter clutch winding 283w is opened and they are deenergized. At contacts 283b the energizing circuit for machine relay winding 286w is opened and this relay is deenergized. Its contacts 286a are reclosed to energize machine clutch relay winding 287w. In turn its contacts 287a are opened to deenergize machine brake winding 57w and its contacts 287b are closed to reenergize machine clutch winding 58w for the purpose of restoring the driving connection between the motor 17 and the stirred casing handling machine 3 and particularly with the severing machine 93.

In the event that the splice detecting contacts 258a should be closed as a result of the occurrence of a splice in the unshirred casing 4 at a time when cam operated contacts 271a are open or cam operated series connected contacts 274a and 275a are open, no control function

is performed. The reason for this is that the setting of these contacts for operation is such that if the splice 242 is detected at a time when these contacts are not closed, it will then appear in the next shirred strand just past the locus of severing which is the position that it is desired that the splice appear. Accordingly, it is unnecessary to stop either the operation of the shirring head 31 or the operation of the severing machine 93 under these circumstances.

It will be recalled that the carriage 116 is reciprocated from right to left, as viewed in FIGS. 1-2, for each shirred strand 115 and then from left to right to repeat the operation for the next shirred and severed strand under the control of the carriage reciprocating cam 167 which rotates through a complete revolution for each shirred strand. The movement of the follower roll 165 in the cam groove 166 on the carriage reciprocating cam 167 and thereby the movement of the carriage 116 through a complete cycle is indicated by the curve 294 in the chart shown on FIG. 11. Here the abscissae represent degrees of rotation of the drum cam 165 with the zero position being chosen to correspond to the position where the carriage 116 is at the right end of its stroke with the carriage jaws 119 poised to engage the end of the strand 115 of shirred casing after it has been severed from the following shirred casing 43 adjacent the compaction rolls 44-45. As indicated by the curve 294, and described hereinbefore, the follower roll 165 is operated in accordance with the shape of the cam groove 166 to move the carriage 116 at varying speeds or to hold it first, for compressing the shirred strand, as indicated at 233 in FIG. 3, against the clamp members 65-65, then to remain motionless to hold the shirred strand 233 compressed against clamp members 65-65, thereafter, on opening the clamp members 65-65 to transfer the shirred and compressed strand 233 onto the receiving mandrel 187, then to dwell and finally to return to the initial position.

During the time that the carriage 116 is being moved according to the curve 294, the carriage jaws 119 are operating as shown by curve 295. At the initial position, the carriage jaws 119 are opened but, by the time that the carriage reciprocating cam 167 has rotated through about 30°, the follower roll 141 on the carriage jaw operating cam 143 has caused the carriage jaws 119 to close into juxtaposition with opposite sides of the floating mandrel 22 in order to engage the severed and reshired end of the shirred strand 115 for the purpose of moving it along the floating mandrel 22 together with the movement of the carriage 116 in the manner described. The carriage jaws 116, as the curve 295 indicates, remain closed until the shirred strand has been transferred onto the receiving mandrel 187 that is in alignment with the floating mandrel 22. Then when the carriage reciprocating cam 167 has been rotated through about 240°, the carriage jaws 119 are opened and remain open until the next cycle of operation of the carriage 116 is initiated.

The floating mandrel is held substantially stationary throughout the operation of the machine, i.e. is held against endwise movement and/or against rotation about its longitudinal axis by clamp members 65-65 or by receiving mandrel 187. The supporting of the floating mandrel in a substantially stationary position throughout the operation of the machine is in marked contrast with the reciprocal movement of the shirring mandrel in certain prior art shirring machines, such as that shown in Korsgaard United States Patent 2,583,654.

Normally the floating mandrel 22 is held against endwise movement and against rotation about its longitudinal axis by clamp members 65-65. Curve 296 shows the operation of cam members 65-65 under the control of the follower roll 75 as determined by the shape of cam groove 76 in mandrel clamp cam 77. At the time that the carriage 116 starts to move from right to left, the clamp members 65-65 engage and hold the floating mandrel 22 against movement. It is necessary to move the

clamp members 65-65 out of holding engagement with the floating mandrel 22 in order to permit the shirred and compressed strand 115 to be transferred to the receiving mandrel 187 in alignment therewith. Accordingly, after the carriage reciprocating cam 167 has rotated through about 120° and while its jaws 119 are holding the shirred strand compressed against the clamp members 65-65, they are opened as a result of movement of follower roll 75 in the cam groove 76 in the mandrel clamp cam 77. The clamp members 65-65 remain unclamped or open during the transfer of the shirred strand, as indicated by curve 294, from the floating mandrel 22 onto the receiving mandrel 187 in alignment therewith. Then after the transfer has been completed, the clamp members 65-65 are again closed to engage the floating mandrel 22 and hold it against movement throughout the remainder of cycle of operation.

During the time that the clamp members 65-65 are out of engagement with the floating mandrel 22, it must be held against movement and for this purpose the receiving mandrel 187 in alignment therewith is moved into endwise engagement with it as indicated by curve 297. This curve traces the movement of follower roll 191 in the cam groove 192 of the receiving mandrel shifter cam 193. At the start of the movement of the carriage 116 from right to left, the receiving mandrel 187 in alignment with the floating mandrel 22 is withdrawn as indicated by the initial portion of curve 297. Prior to the unclamping of the clamp members 65-65 from the floating mandrel 22, the receiving mandrel 187 aligned with the floating mandrel 22 is moved endwise under the control of follower roll 191 and operation of the receiving mandrel shifter arm 188 to engage the floating mandrel 22. Following this, as indicated by curve 296, the clamp members 65-65 are opened. While they remain disengaged from the floating mandrel 22, it is held against movement by the receiving mandrel 187. Then, following reclamping of the floating mandrel 22 by the clamp member 65-65, as shown by curve 296, the receiving mandrel 187, now having the shirred strand transferred thereto, is moved endwise out of engagement with the floating mandrel 22 under the control of the follower roll 191 as determined by the shape of the cam groove 192 in the receiving mandrel shifter cam 193. The receiving mandrel shifter arm 188 then remains in the withdrawn position during the remainder of the cycle.

The turret 177 is indexed twice for each cycle of operation of the carriage 116. This is shown by curve 298 which is indicated as being in two sections. It reflects the movement of the follower rolls 182 in the cam groove 183 on the turret index cam 184. It will be observed that the turret 177 is indexed to rotate the receiving mandrels 187 to the next position only during the time that the clamp members 65-65, as represented by the curve 296, are in the clamped position with the receiving mandrel 187 in alignment with the floating mandrel 22 in retracted position as indicated by curve 297.

At the lower portion of the chart shown in FIG. 11 there are illustrated the various times that the cam controlled contacts 221a, 222a, 223a, and 271a to 275a are closed or open. The times during the cycle of operation of the carriage 116 or of the rotation of the carriage reciprocating cam 167 that these contacts are closed are indicated by the horizontally lined portions associated with the respective reference characters applied to the contacts. The times during which the contacts are opened are represented by unlined portions of the chart.

Contacts 221a are closed to energize the solenoid 174 for controlling the operation of 3 way solenoid valve 173 for the air operator 172 at the beginning of the part of the movement of the carriage 116 when the shirred strand on the floating mandrel is being compressed against the clamp members 65-65. The air operator 172 assists in this operation and also in the transfer of the shirred casing from the floating mandrel 22 to the receiving

mandrel 187. During the second hold or dwell period of the carriage 116 and just before it is returned, the contacts 221a are opened to deenergize the solenoid 174 to exhaust the compressed air to the atmosphere for free retraction of the connecting rod 171 to the initial position along with the carriage 116.

The contacts 222a, which control the operation of the solenoid 208 of the solenoid valve 207 that is associated with the compressor hydraulic operator 206 are closed to extend the connecting rod 205 and move the pusher 204 for, in turn, moving the next compressor-doffer 199 to compress the stirred strand on the associated receiving mandrel 187 against the compressor surface 202 of the compressor member 201, FIG. 4. The contacts 222a remain closed, as the chart shown on FIG. 11 indicates, while the turret 177 indexes one position in order to place the compressor-doffer 199 in position where, as a result of the next indexing step, it will react against holding surface 210 of holding member 209. Thereupon the contacts 222a are opened and the pusher 204 together with the connecting rod 205 are retracted as a result of the deenergization of the solenoid 208 and shifting of the solenoid valve 207 to permit reverse operation of the hydraulic operator 206.

Contacts 223a are closed, as shown by the chart in FIG. 11, at the end of an indexing operation, as indicated by curve 298, to energize the solenoid 217 of the solenoid valve 216 and cause the doffer hydraulic operator 215 to extend the connecting rod 214 and doffer yoke 213. At this time the doffer yoke 213 engages the compressor-doffer 199 on the receiving mandrel which is in the doffing position, as indicated in FIG. 4 of the drawings. As a result of the energization of solenoid 217 by closure of contacts 223a, the doffer hydraulic operator 215 is caused to extend the connecting rod 214 with the result that the stirred and compressed strand 235 is doffed as indicated in FIG. 4.

Under normal operating conditions, absent a splice, the stirring machine 1 operates in accordance with the functions portrayed by curves 294 to 298 and contacts 221a, 222a and 223a are periodically closed and opened at the times and for the times shown on the chart appearing in FIG. 11.

The chart shown in FIG. 11 also indicates the times during which contacts 271a to 275a are closed and opened. As previously pointed out contacts 271a are closed at a time immediately after the severing operation has been performed by the scoring yoke or cutter 99 under the control of the severing machine 93. These contacts remain closed for a major portion of the period of operation of the severing machine 93. They are opened at a time corresponding to the positioning of a splice, if present, slightly beyond the locus of severing.

Contacts 272a and 273a are closed for brief intervals and the time during which their closures overlap is the time during which a circuit therethrough is completed. It will be noted that this time is shortly after the carriage 116 starts to move from right to left and this corresponds to a time slightly after the severing operation has been completed so as to permit the starting of the stirring head 31 at such time that the next stirred strand will be of full length. As pointed out, a single set of contacts can be employed in lieu of the series connected contacts 272a and 273a provided that their times of closure and opening can be accurately adjusted under the control of the cam shaft 80 or auxiliary cam shaft 227.

Contacts 274a and 275a are both closed for only a brief interval to complete a circuit just prior to the closure of the contacts 271a. It has been pointed out that the time of joint closure of contacts 274a and 275a corresponds to the detection of a splice 242 which, if undetected, would appear at the locus of severing accomplished by the scoring yoke or cutter 99. This is a short interval and the degree of overlap has been so indicated in the chart shown on FIG. 11. Here again a single set of

contacts can be employed provided their times of closure and opening can be accurately synchronized with the rotation of the cam shaft 80 of auxiliary cam shaft 227.

FIGS. 12 to 17 show the details of construction of the stirred casing severing means or severing machine 93. It is located in and on a housing 94 that is positioned centrally underneath the floating mandrel 22 and is arranged to be operated periodically by the shaft 100 when the one revolution clutch 101, FIG. 2, is released by movement by the detent 103 under the control of the trip cam 114. The time between successive rotations of the shaft 100 determines the length of the stirred strand 115 on the floating mandrel 22. The severing machine 93 is operated once for each stirred strand 115 for severing it from the following stirred casing 43.

In order to facilitate the separation of the folds and pleats of the stirred casing 43, the holding finger or digger 95 has an inclined face 301 and to hold back the stirred casing 43 from the strand 115 that is to be severed, a vertical face 302 is provided. The holding finger or digger 95, FIG. 14, is secured to and projects upwardly from the upper end of a vertical rod 303 which has a longitudinal opening 304 near the upper end through which a stud 305 projects. The stud 305 is stationary relative to the vertical rod 303 and a coil compression spring 306 is interposed between the upper side of the stud 305 and the upper end of the longitudinal opening 304 for the purpose of biasing upwardly the vertical rod 303 and the holding finger or digger 95 mounted thereon. The upward movement of the holding finger or digger 95 is limited by the floating mandrel 22 or by the surrounding stirred casing 43 as the case may be. The stud 305 extends from a carrier block 307 which is mounted for horizontal movement between guide rails 308, FIG. 12, that are carried at their ends by end brackets 309-309 which are mounted on the upper side of the housing 94. It will be observed that the shafts 98-98 are rotatably mounted at their ends in the end brackets 309-309.

It is desirable that the holding finger or digger 95 move along the floating mandrel 22 at the speed that the casing 43 is stirred thereon while it is performing its holding operation. It is for this purpose that the carrier block 307 is slidably mounted on the guide rails 308. In order to move the carrier block 307 horizontally to perform this function it is connected by a pin 312 to a block 313, FIG. 15, which is slidably mounted in the bifurcated upper end of a driving lever 314 which has a hub 315 at its lower end for rotatably mounting on a shaft 316 which is mounted at its ends on suitable bearings carried by side walls 317-317 of the housing 94. The driving lever 314, FIG. 15, is provided with a follower roll 318 intermediate its ends that is arranged to engage a cam groove 319 in a box type digger and cutter cam 320 which is fast on the shaft 100.

The vertical movement of the rod 303 and of the holding finger or digger 95 is controlled by the interaction of a stud 321, which projects laterally from the lower end of the vertical rod 303, and the under surface of an upper ledge 322 of a transverse head member 323. The transverse head member 323 is moved upwardly at a certain time in the cycle of operation of the severing machine 93 to permit the spring 306 to move the vertical rod 303 and the holding finger or digger 95 upwardly. The transverse head member 323 is secured by a bolt 324 to the upper end of a control rod 325 which is guided in a sleeve 326 that is stationarily mounted in the housing 94. At its lower end the control rod 325 is provided with a clevis 327 through the arms of which a transverse pin 328 extends for connecting the clevis 327 to the distal end of an operating lever 329. The operating lever 329 is rotatably mounted on a horizontal shaft 330 which is suitably journaled at its ends on the side walls 317-317 of the housing 94. A follower roll 331 is mounted intermediate the ends of the operating lever 329 for a purpose that will be described presently. The distal end of the

operating lever 329 is biased upwardly by a coil tension spring 332 the lower end of which is connected to the pin 328 and the upper end of which is connected to a pin 333 which extends from the upper end of the stationary sleeve 326. The follower roll 331 is held in engagement with the peripheral surface of the finger and cutter cam 320 by the spring 332.

It will be observed that the surface of the finger and cutter cam 320 is divided into three portions. One portion 334 of the cam surface is at a maximum distance from the axis of rotation of the digger and cutter cam 320 and holds the operating lever 329 in its lowermost position with maximum tension on the spring 332. This is the normal or at rest position of the digger and cutter cam 320 in which the holder or digger finger 95 is withdrawn from the holding position. When the shaft 100 is rotated from the position shown in FIG. 15 of the drawings, the digger and cutter cam 320 is rotated to position the follower roll 331 in engagement with a portion 335 of the cam surface which is nearer to the axis of rotation of the digger and cutter cam 320. This permits the spring 332 to move the control rod 325 upwardly and carries with it the transverse head member 323. As a result the upper ledge 322 moves upwardly through a corresponding distance and the spring 306 is permitted to move the vertical rod 303 together with the holding finger or digger 95 upwardly to perform the holding operation.

It will be recalled that the pinch roll brackets 97-97 are mounted on horizontally extending shafts 98-98 for movement toward and away from each other in order to move the pinch rolls 96-96 toward and away from opposite sides of the floating mandrel 22 to engage the shirred casing for extending a portion of it to permit the performance of the severing operation and to reshirk the portion of the casing that is unshirked during this interval. The pinch roll brackets 97-97 are mounted on support arms one of which is indicated at 340 in FIG. 12 of the drawings. Each support arm 340 has a hub 341 which is fast on the respective shaft 98. Coil springs 342-342 surround the left ends of the shafts 98 and are secured thereto at one end and at the other ends to the associated end bracket 309 for normally biasing the pinch roll brackets 97-97 and parts associated therewith toward each other. In order to move the pinch roll brackets 97-97 away from each other and move the pinch rolls 96-96 out of operative engagement with the shirred casing on the floating mandrel 22 for the purposes described, hubs 343-343, FIG. 15, are fast on the shafts 98-98 and are provided with operating arms 344-344 the lower ends 345-345 of which are arranged to be engaged by roll spreading cams 346-346. The roll spreading cams 346-346 have sloping engaging portions 347-347 for engaging the lower ends 345-345 of the operating arms 344-344 to move them onto the respective cams 346-346 for opening or spreading the pinch roll brackets 97-97 against the biasing action of the springs 342-342. The roll spreading cams 346-346 also are provided with sloping disengaging portions 348-348 to permit gradual transition of the lower ends 345-345 of the operating arms 344-344 from the respective operating surfaces of the roll spreading cams 346-346.

Not only are the pinch rolls 96-96 mounted for rotation about their longitudinal axes but also they are mounted to be moved bodily and at a relatively high speed along the floating mandrel 22. Their speed is substantially higher than the speed at which the casing 43 is shirked by the shirring head 31. For this purpose the pinch rolls 96-96 are rotatably mounted on roll carrying slides 349-349 which are slidably mounted on the pinch roll brackets 97-97 and are movable relative to guides 350-350 which extend from the pinch roll brackets 97-97. The roll carrying slides 349-349 are engaged by flattened ends 351-351, FIG. 15, on a pin 352 which extends transversely through the distal end of a pinch roll moving lever 353 which has a hub 354 at

its lower end that is mounted for rotation on a horizontal shaft 355 that is journaled at its ends in suitable bearings carried by the walls 317-317 of the housing 94. A follower roll 356 extends laterally intermediate the ends of the pinch roll moving lever 353 to engage a cam groove 357 in a pinch roll cam 358 which is fast on the shaft 100. It will be understood that the roll carrying slides 349-349 and the pinch rolls 96-96 mounted thereon are moved horizontally along the floating mandrel 22 as controlled by the movement of the follower roll 356 in the cam groove 357 on rotation of the pinch roll cam 358.

FIG. 13 shows how the pinch rolls 96-96 are mounted for rotation. As here shown each pinch roll 96 is mounted on a pinch roll shaft 359 which is suitably journaled in the respective roll carrying slide 349. Each pinch roll shaft 359 is provided with a pinion 360 which is arranged to engage with a juxtaposed rack 361. There are two racks 361 and they are stationarily mounted on the respective pinch roll brackets 97-97. Since they are stationary and since the shafts 359 on which the pinch rolls 96-96 are mounted move with the roll carrying slides 349-349, the pinch rolls 96-96 are rotated in the directions indicated by the arrows thereon for the purpose of reshirk the folds or pleats of the shirred strand 115 which have become unfolded to permit the severing operation to be performed.

It will be recalled that the scoring yoke or cutter 99 is provided to perform the severing operation. This device is shown in FIGS. 14 and 15 as including arms 364-364 which are provided with arcuate surfaces 365-365 which face each other and which are arranged to engage opposite sides of the floating mandrel 22 which is cylindrical in cross section. As a result the engagement between the arms 364-364 and the floating mandrel 22 takes place substantially at two points because of the contacting convex curved surfaces. While the arms 364-364 are shown as being formed integrally with the main portion of the scoring yoke or cutter 99, it will be understood that a pair of rigid relatively large diameter wires can be employed to provide the bifurcated construction with the arms extending at a slight angle away from each other to facilitate engagement with the casing on the floating mandrel 22 that is to be scored for the purpose of initiating the severing operation.

The scoring yoke or cutter 99 is positioned in the upper end of a vertical rod 366 which is guided in and is movable with the carrier block 307 in somewhat the same manner that the vertical rod 303 is mounted therein. At its lower end the vertical rod 366 is provided with a laterally extending stud 367 which, as shown in FIG. 17, is somewhat longer than the stud 321 which is mounted on the lower end of the vertical rod 303 underneath the upper ledge 322. The stud 367 projects over the upper surface of a lower ledge 368 on the transverse head member 323 and into a slot 369 that is formed therein which permits the stud 367 to be moved horizontally relative to the transverse head member 323 which only has vertical movement. When the transverse head member 323 is moved upwardly, as urged by the spring 332 under the control of the digger and cutter cam 320 in the manner described hereinbefore, the upper surface of the lower ledge 368 engages the stud 367 and moves the vertical rod 366 upwardly through an extent sufficient to move the arms 364-364 of the scoring yoke or cutter 99 into scoring or cutting position on opposite sides of the floating mandrel 22.

FIGS. 18 to 27 show the sequence of operations that takes place when the severing operation is performed as dictated by the trip cam 114. For illustrative purposes the pinch rolls 96-96 are here illustrated as always being vertically positioned. However, it will be understood that, when they are separated, they are inclined at the slight angles away from each.

FIGS. 18-19 show the shirked strand 115 on the float-

ing mandrel 22 with the pinch rolls 96—96 retracted and with the holding finger or digger 95 and the arms of the scoring yoke or cutter 99 in their lowermost positions. The pinions 360 are indicated as being at the right ends of the stationary racks 361—361.

FIGS. 20—21 show the next step in the operation of severing in which the holding finger or digger 95 has been permitted to move upwardly under the influence of the spring 306 under the control of the cam portion 335 of the digger and cutter cam 329. At this time no upward movement of the scoring yoke or cutter 99 takes place. At about the same time that the holding finger or digger 95 moves upwardly, the pinch rolls 96—96 are moved inwardly to separate the folds or pleats of the shirred casing 43 in order to provide an unfolded portion as indicated at 370 in FIG. 22 of the drawings. It will be observed here that the pinch rolls 96—96 have been moved slightly to the left from their positions as shown in FIGS. 18 and 20 and, since they are moving relative to the racks 361—361, they are being rotated.

The unfolded portion 370 is provided in order to permit the arms 364—364 of the scoring yoke or cutter 99 to move upwardly past the floating mandrel 22, as indicated in FIG. 23, and to score those portions of the unfolded portion 370 of the casing against the surface of the floating mandrel 22. This scoring action initiates tears on opposite sides of the floating mandrel 22 and, since the pinch rolls 96—96 continue to be moved to the left away from the holding finger or digger 96, as shown in FIG. 24, the unfolded portion 370 is tensioned. Sufficient force is applied to complete the severing operation which is initiated at the scored portions 371, on opposite sides of the floating mandrel 22 with the result that a fish tail end 372 is provided at the right end of the unfolded portion 370.

At this time, as indicated in FIG. 25, the semi-circular ends 120—120 of the carriage jaws 119—119 are separated at the locus of severing preparatory to engaging the shirred strand 115 and moving it along the floating mandrel 22.

As shown in FIG. 26, the pinch rolls 96—96 have been moved to the left end of their stroke end, since they are rotating in a manner described, they reshrink the unfolded portion 370 associated with a right end of the shirred casing 115 to receive the semi-circular ends 120—120 or the carriage jaws 119—119 which, as shown in FIG. 27, are moved to encircle the floating mandrel 22 and then are moved therewith in the manner described, to move the shirred strand 115 along the floating mandrel 22, to compress it thereon against the clamp members 65—65 and ultimately to transfer it to the receiving mandrel 187 in alignment therewith. Also, as shown in FIG. 27, the holding finger or digger 95 and the scoring yoke or cutter 99 are moved downwardly and the pinch rolls 96—96 are moved apart, thereby completing the operations that take place to sever the shirred strand 115 from the following shirred casing 43. It will be understood that the operation of the pinch roll moving lever 353 is such that the pinch rolls 96—96 are returned to their initial positions as shown in FIG. 18 of the drawings.

FIGS. 28, 29 and 30 show further details of the operating means for rotating the upper and lower support rails 117 and 118 about their longitudinal axes for controlling the operation of the carriage jaws 119—119. It will be observed that the rails 117—118 are journaled in bearings 377—378 which are mounted in spaced relation, one above the other, on a vertical support member 379 which is mounted on the frame of the shirring machine 1. A coil tension spring 380 is connected at its ends to pins 381 and 382 which are located, respectively, on the upper and lower operating arms 131—132 for biasing them toward each other. It will be recalled that the operating rod 137 is connected at 136 to the link 134 which is pivoted at 133 to the distal end of the upper operating arm 131. The link 134 has a longitudinal slot 135

through which a pin 384, mounted on the lower operating arm 132, extends. When the pin 384 is located at the upper end of the slot 135 and the operating rod 137 is moved downwardly, both of the operating arms 131—132 are rotated to effect corresponding rotations of the upper and lower support rails 117—118 in a clockwise direction as viewed in FIG. 30, for example. However, when the operating rod 137 is moved upwardly, only the upper operating arm 131 is moved positively while the lower operating arm 132 is moved under the control of the spring 380.

Any suitable means can be provided for insuring that the upper and the lower arms 131 and 132 are securely fastened to the upper and lower support rails 117—118 respectively. For this purpose clamp bolts 385—386 can be employed together with keys 387—388. Grooves 389—389 and 390—390 are provided in the opposite sides of the upper and lower support rails 117—118 for a purpose that will be apparent presently.

Extending laterally from the vertical support member 379 is a boss 391 in which an adjustable stop bolt 392 is threaded and held in place by a lock nut 393. The adjustable stop bolt 392 projects beyond the boss 391 for engaging a radially extending arm 394 on the lower operating arm 132. By varying the position of the adjustable stop bolt 392, it is possible to vary the position of the arm 394 and thereby of the lower operating arm 132 to change the position to which it is rotated in a counterclockwise direction by the spring 380.

The details of construction of the carriage 116 are shown in FIGS. 31, 32 and 33. There it will be noted that the carriage plates 129—129 extend laterally from a carriage frame 396 on which the carriage bearings 130—130 are mounted whereby the carriage 116 is movable along the upper and lower support rails 117—118 through the agency of rolls 397—397 and 398—398 which are suitably mounted in frames 399—400, respectively, which, in turn are journaled in the carriage bearings 130—130. It will be noted that the rolls 397—397 interfit with and roll along the grooves 389—389 in opposite sides of the upper support rail 117. Likewise the rolls 398—398 interfit with and roll along grooves 390—390 that are provided along the opposite sides of the lower support rail 118. This arrangement insures that the carriage 116 will be held in proper position with respect to the floating mandrel 22 and thereafter with respect to the receiving mandrel 187 in alignment therewith while at the same time it permits movement of the carriage 116 with a minimum of friction along the upper and lower support rails 117—118. An arm 401 extends laterally from the frame 399 on the upper support rail 117 and it has spaced rectangular end portions 402 which are provided with rectangular slots 403 along which slides 404 move for supporting the transverse pin 125 on which the links 124—124 are mounted. This construction permits the pin 125 to move upwardly along the vertical lower slot portions 127—127 of the carriage plates 129—129 and also to follow the arcuate upper slot portions 128—128 when the upper support rail 117 is rotated about its longitudinal axis on operation of the operating rod 137 accompanied by rotation of the arm 401. Such movement is accompanied by corresponding movements of the pivots 123—123 and operation of the carriage jaws 119—119

not only to move the semi-circular ends 120—120 into operative position with respect to the floating mandrel 22 and subsequently out of operative position with respect to the receiving mandrel 187 in alignment therewith but also to move the carriage jaws 119—119 and their semi-circular ends 120—120 upwardly in order to permit the return of the carriage 116 to its initial position when the clamp members 65—65 have been reclosed after the shirred strand 115 has been transferred from the floating mandrel 22 onto the receiving mandrel 187 in alignment therewith. Similarly the arm 122 extends from the frame 400 mounted on the lower support rail 118 and it has rectangular end portions 405 provided with rectangular slots

406 in which slides 407 are movably mounted for supporting the pivot 121 which permits the carriage jaws 119—119 to move in the manner described for moving their semi-circular ends 120—120 into and out of operative engagement with the floating mandrel 22 and the receiving mandrel 187 in alignment therewith.

It will be recalled that the spring 380 interconnects the upper and lower operating arms 131—132, FIGS. 29—30. As shown in FIG. 29, the spring 380 holds the arm 394 on the lower operating arm 132 against the adjustable stop bolt 392 and the slot 135 provides lost motion between the upper and lower operating arms 131—132 to the end that, when the operating rod 137 is moved downwardly, it causes conjoint rotation of the upper operating arm 131 and of the upper support rail 117 while the lower operating arm 132 and the lower support rail 118 remain stationary until the upper end of the slot 135 engages the pin 384 whereupon the lower operating arm 132 and the lower support rail 118 are rotated. The initial movement of the upper operating arm 131 on downward movement of the operating rod 137 moves the transverse pin 125 upwardly along the vertical lower slot portions 127—127 from the position shown in FIG. 32 and thereby causes the upper ends of the carriage jaws 119—119 to move toward each other and their semi-circular lower ends 120—120 to move away from the receiving mandrel 187 in alignment with the floating mandrel 22. Thereafter, as described, the lower support rail 118 is rotated to lift the pivot 121 and permit the upward movement of the carriage jaws 119—119 which takes place while the transverse pin 125 moves along the arcuate upper slot portions 128—128. On the upward movement of the operating rod 137, the foregoing sequence of operations is reversed but the lower operating arm 132 is not positively driven. Rather it is rotated together with the lower support rail 118 under the control of the spring 380 and the extent of rotation is controlled by adjusting the stop bolt 392. This makes it possible to position accurately the carriage jaws 119—119 and their semi-circular ends 120—120 in proper operative relation with respect to the floating mandrel 22 and the receiving mandrel 187 in alignment therewith and independently, to a considerable extent, of the position of the operating rod 137 and its connections to its operating mechanism.

FIGS. 34, 35 and 36 show in more detail the manner in which the clamp members 65—65 are constructed and operated. It will be observed that a frame end casting 412 is employed and that it is mounted on a support plate 413 which forms a part of the frame for the stirring machine 1. A hexagonal core or turret shaft 414, which is rotatable about its longitudinal axis parallel to the longitudinal axis of the floating mandrel 22, extends to the left of the frame end casting 412 and it has a cylindrical end portion 415 that is journaled in a bearing 416 which is mounted on the compressor member 201 against whose surface 202 the stirred and compressed strands 234 are held under compression. The compressor member 201 is in the form of a plate that is generally semi-circular in shape and is secured to the frame end casting 412 by suitable bolts 201'.

The clamp members 65—65 include clamp jaws 417—418 which are secured by bolts 419—419 to the inner ends of slides 420—420 which are guided for horizontal sliding movement toward and away from each other between pairs of guide members 421—421 which are suitably secured to the frame end casting 412. As shown in FIG. 36 each of the slides 420 is provided with a longitudinal slot 422 through which bolts 423—423 extend between the pairs of guide members 421—421. Spacing collars 424—424 are associated with the bolts 423—423 in each slot 422 to guide the respective slide 420 in a horizontal endwise movement. The outer ends of the slides 420—420 are pivotally connected at 66—66 to pairs of links 425—425 which, in turn, are pivoted at 426—426 to the upper ends of the arms 427—428 which

form parts of the bell cranks 67—67. Arms 429—429 are welded to the lower ends of the arms 427—428 and they are pivoted at 68—68 onto the ends of the shafts 430—431 which extend through the frame end casting 412 and form a part of the frame of the stirring machine 1. It will be noted that the distal ends of the arms 429—429 are pivotally connected at 70—70 to the upper ends of the operating rods 71—71.

The arm 427 at the left side of the frame end casting 412, as viewed in FIG. 35, is offset centrally to provide an opening 432 through which an inclined tray 433 extends to receive the completed, stirred and compressed strands 235 as they are doffed from the receiving mandrels 187 when they are located in the doffing position.

FIGS. 37, 38 and 39 show at an enlarged scale the details of construction of the clamp members 65—65. In order to hold the floating mandrel 22 against endwise movement as well as against rotation about its longitudinal axis, the trailing end 63 thereof is provided with a radially extending recess 436 that is arranged to receive a support pin 437 which extends from the clamp jaw 418. Since the trailing end 63 of the floating mandrel 22 is received between the clamp jaws 417—418 at which time the support pin 437 interfits with the recess 436, the floating mandrel 22 is thereby held against endwise movement as well as against rotation about its longitudinal axis.

The floating mandrel 22 is provided with a longitudinally extending central air passageway 22' to permit air to flow under pressure to its leading end 21 for inflating the casing at 23. Within the trailing end 63 of the floating mandrel 22 there is a central counter bore 438 with which the air passageway 22' communicates and within which there is positioned a cylindrical plug 439 with a press fit. The cylindrical plug 439 has a central passageway 440 which extends part way along its longitudinal axis from the left end as viewed in FIG. 37 and a passageway 441 communicates therewith. The passageway 441 extends transversely through the trailing end 63 of the floating mandrel 22 and through the wall of the cylindrical plug 439 into the central passageway 440 therein. At its outer end the transverse passageway 441 communicates with a passageway 442 in the clamp jaw 417 through which air is supplied from a pipe 443 which provides the air connection 69 previously described. It will be understood that air under pressure flows through the pipe 443, passageway 442, transverse passageway 441, central passageway 440, into a counter bore 444 and thence through longitudinal grooves 445 along the cylindrical plug 439 to the right end of the counter bore 438 and thence into the air passageway 22' in the floating mandrel 22. Such flow of air takes place when the clamp jaws 417—418 are closed, as shown in FIGS. 37—38. The air under pressure causes a valve disc 446 to close off the right end of a central passageway 447 in a cylindrical connector 448 which has a press fit with a counter bore 449 at the left end of the trailing end 63 of the floating mandrel 22. When the valve disc 446 closes off the central passageway 447, the air flows under pressure to air passageway 22' in the floating mandrel 22 from the pipe 443.

It will be recalled that the stirred strand 115 is transferred from the floating mandrel 22 to the receiving mandrel 187 in alignment therewith on opening of the clamp members 65—65. At that time it is necessary to transfer the air supply to the floating mandrel 22 from the pipe 443 through the clamp jaw 417 to the receiving mandrel 187 so aligned. Also the arrangement is such that the floating mandrel 22 is held against endwise movement and rotation about its longitudinal axis by this receiving mandrel 187 since, when the clamp members 65—65 are opened, the support pin 437 no longer interfits with the recess 436. To provide these functions the cylindrical connector 448 is provided with a tapered end 450 which snugly interfits with a tapered opening 451 in

each of the receiving mandrels 187 when they are moved, one by one, into the position shown in FIG. 37 under the control of the receiving mandrel shifter cam 193. In this position a transverse pin 452 in the leading end of each of the receiving mandrels 187 interfits with a transverse groove 453 in the left end of the cylindrical connector 448. This mechanical connection serves in lieu of the support pin 437 to prevent rotation of the floating mandrel 22 about its longitudinal axis and, since each receiving mandrel 187 is held in the position shown in FIG. 37 during an interval long enough to permit the transfer of the stirred casing 115 thereto from the floating mandrel 22, the latter likewise is held against endwise movement. Once the floating mandrel 22 is supported by the receiving mandrel 187 in the manner described, air under pressure flows through an air passageway 187' centrally of the receiving mandrel 187 through a counter bore 454 in the left end of the cylindrical connector 448 and through the central passageway 447. Here the air pressure is applied to the valve disc 446 and it is moved to close off the left end of the central passageway 440. Then air flows through the counter bore 444 and the longitudinal grooves 445 into the right end of the counter bore 438 and thence to the air passageway 22' in the floating mandrel 22. In this manner air always is supplied through the floating mandrel 22.

FIGS. 40, 41, 42 and 43 show the details of construction of the turret 177. It will be noted that a frame end casting 460 is mounted on the support plate 413 in alignment with the frame end casting 412 at the other end. Also, it will be noted that the shafts 430—431 are also mounted on frame end casting 460. Thus, they span the frame end castings 412—461. The frame end casting 460 is provided with a bearing 461 to receive a cylindrical end portion 463 of the hexagonal core or turret shaft 414. The core or turret shaft 414 is driven by the mitre gears 179 in the manner previously described to index it successively to each of the twelve positions.

Formed in the frame end casting 460 is an annular internal groove 463 that is provided for guiding rolls 464 therealong. The rolls 464 extend radially outwardly from the receiving mandrel holders 178 from which the receiving mandrels 187 extend laterally. It will be recalled that the receiving mandrel holders 178 and the respective receiving mandrels 187 are retracted in all positions of the core or turret shaft 414 except in the position where a receiving mandrel 187 is in alignment with the floating mandrel 22 at which time it is shifted endwise into engagement with the floating mandrel 22 for holding it in position against endwise movement and against rotation about its longitudinal axis and also for the purpose of having the stirred casing 115 transferred thereto. In order to permit the receiving mandrel holder 178 carrying the receiving mandrel 187 in alignment with the floating mandrel 22 to be shifted in this manner, a break 465 is provided at the top of the annular internal groove 463. Only in this position is the roll 464 movable horizontally with respect to the annular internal groove 463. In this position the roll 464 is moved into a recess 466 in an arm 467 that is secured by a bolt 467' to a slide 468 which is movable endwise along the outer periphery of the bearing 461. The slide 468 is engaged at its upper and lower sides by a yoke 469 which constitutes the shifter arm 188 that is fast on the upper end of and rotates with the vertical shaft 189 under the control of the receiving mandrel shifter cam 198 in the manner previously described.

FIG. 43 shows how the receiving mandrel holders 178 are slidably mounted on the hexagonal core or turret shaft 414. Here it will be observed that a slide 470 is secured by countersunk bolts 471 to each receiving mandrel holder 178 and that the respective sides of the slides 470 underlie guide plates 472 which extend along the hexagonal core or turret shaft 414 along rectangular keys 473, both being secured to the turret shaft 414 by bolts

473'. Since the core or turret shaft 414 is hexagonal, as shown, the slides 470 can move along the respective hexagonal side underneath the guide plates 472 and between the keys 473 under the control of the receiving mandrel shifter arm 188 or the yoke 469.

It will be noted in FIGS. 41 and 43 of the drawings that the air passageways 196 extend radially from an axial air passageway 474 in the turret shaft 414 and communicate with the air passageway 197 which extends through the respective slide 470 into the mandrel holder 178 when it occupies the position shown in FIG. 41 where the receiving mandrel 187 at the top of the turret shaft 414 is shown as having been moved forwardly into supporting engagement with the floating mandrel 22. It will be understood that the left end of the core or turret shaft 414 forms the air manifold 195 previously referred to and it will be noted that the air passageway extends through the cylindrical end portion 462 and is connected by a flexible joint 475 to the air supply connection 189.

FIG. 44 shows how each compressor-doffer 199 is moved along the respective receiving mandrel 187. Here it will be observed that each receiving mandrel 187 is threaded at 478 into its receiving mandrel holder 178 and is held in position thereon by a lock nut 479. Each compressor-doffer 199 is mounted on a slide 480 in a manner similar to that in which each receiving mandrel holder 178 is mounted on its slide 470 to move along the respective hexagonal surface of the core or turret shaft 414 and to be guided there along by the guide plates 472 and keys 473. At its right end the compressor-doffer 199 has an insert 481 which surrounds the receiving mandrel 187 and holds an annular brush 482 in position to which a lubricant is supplied for lubricating the surface of the receiving mandrel 187. Extending outwardly from each compressor-doffer 199 is a roll 483 that is arranged to be engaged by a shoulder 484 at the lower end of the pusher 204 which is mounted at the outer end of and is moved by the connecting rod 205 under the control of the compressor hydraulic operator 206. The upper end of the pusher 204 is guided on a guide rod 485 which is mounted in cantilever fashion on a bracket 486 which is mounted on the frame end casting 460. Also mounted on the bracket 486 is the compressor hydraulic operator 206 and it contains a piston 487 which is connected to the connecting rod 205 and, as will be readily understood, effects movement thereof in one direction or the other depending upon the application of hydraulic pressure to one side or the other.

FIG. 45 shows the manner in which the doffer yoke 213 is mounted to move the compressor-doffer 199 in the doffing position outwardly to doff the completed strand 235 and to return the compressor-doffer 199 to an intermediate position along the receiving mandrel 187 to be engaged by the next stirred strand 115 and moved thereby under the control of the carriage 116 back to the initial position. In FIG. 45 it will be observed that the lower end of the doffer yoke 213 has a slot 491 into which the roll 483 is rotated when the turret shaft 414 is indexed. The movement of the doffer yoke 213 is guided, in part, by a shaft 492 which extends between a bracket 493 on the frame end casting 460 and the frame end casting 412. It is necessary to guide the doffer yoke 213 for the extended distance in view of the fact that it must move the compressor-doffer 199 engaged thereby beyond the outer end of the respective receiving mandrel 187 in order to insure that the strand 235 is completely doffed. It will be noted that the doffer hydraulic operator 215 is mounted on the bracket 493 and that its connecting rod 214 is connected to the doffer yoke 213 intermediate its ends.

It is desirable that provision be made for detecting movement of the floating mandrel 22 out of its normal portion where it is held by the mandrel clamps 65—65 or by the receiving mandrel 187 aligned therewith. Since the floating mandrel 22 is formed of magnetic material,

a magnetic transducer 299, FIGS. 3 and 9, can be located in proximity to the leading end 21 for controlling the operation of proximity contacts 300. As long as the leading end 21 of the floating mandrel 22 remains in predetermined spaced relation to the magnetic transducer 299, the proximity contacts 300 remain closed and the motor 17 continues to be energized. However, should the floating mandrel 22 be moved out of operative position, the magnetic field affecting the magnetic transducer is changed and proximity contacts 300 are opened to deenergize the motor 17. On restoration of the floating mandrel 22 to its operative position, the proximity contacts 300 are reclosed and the motor 17 can be restarted to continue the operation of the stirring machine 1 provided that it is otherwise in condition to operate.

The clutch 12 which controls the driving connection between the shaft 10 and the motor 17 preferably is of a type that permits completion of the driving connection to the head mechanism 2 with a minimum of shock and, after the driving connection is established, maintains the driving connection without slippage. For these purposes a combination electrically operated friction clutch and an electrically operated tooth gear clutch are employed. The friction clutch is energized first to place the head mechanism in operation and then the tooth gear clutch is energized to insure that the driving connection without slippage is maintained. Both clutches are simultaneously deenergized when the driving connection is to be interrupted.

In the operation of the stirring machine 1 as described hereinbefore and illustrated by the curves shown by full lines in FIG. 11 the stirred strand 115 on the floating mandrel 22 is fully compressed as indicated at 233 in FIG. 3 against the clamp members 65-65 by the carriage jaws 119-119 as moved by the carriage 116 in its forward movement. Upon opening of the clamp members 65-65 under the control of the clamp cam 77, the compressed strand 233 expands slightly during its transfer to the receiving mandrel 187 in alignment with the floating mandrel 22. Thereafter, on subsequent indexing of the turret 177, the compressed strand 233 is recompressed and held in the recompressed condition in the manner described until it is subsequently doffed.

In some instances, particularly where longer strands, i.e. 100' or more, or stirred it is desirable to open the clamp members 65-65 before any compression action thereagainst takes place. This permits the stirred strand 115 to be moved with a minimum of friction off of the floating mandrel 22 onto the receiving mandrel 187 in alignment therewith and to be compressed thereon in the direction that the casing 43 is stirred following picking up of the respective compressor-doffer 199 and moving it to engage the stop 200. The continued movement of the carriage 116 with the carriage jaws 119 juxtaposed to the floating mandrel 22 and finally to the receiving mandrel 187 aligned therewith causes the stirred strand 115 to be compressed thereon for the principal part of the extent that it finally is compressed. For example, the stirred strand 115 can be compressed from 70 to 80% of its final compressed length by the movement of the carriage 116, the compression taking place from the last severed end of the stirred strand 115 and in the direction in which it previously was stirred.

Following the partial compression of the stirred strand 115 by the carriage 116 on the receiving mandrel 187 in alignment with the floating mandrel 22, the remaining compression of the stirred and partially compressed strand is effected against the surface 202 of compressor member 201 in the manner previously described by the forward movement of the compressor-doffer 199 under the control of the compressor means 206. It will be observed that the final compression of the stirred and partially compressed strand is effected in a direction opposite to the direction in which the strand previously was stirred and

also that the compression force is exerted from the opposite end.

Where particularly long strands are involved, it is advantageous to effect the compressing actions from opposite ends of the strand in the manner just described in order that the final strand will be substantially uniformly compressed from end to end rather than being compressed more tightly at one end than it is at the other. When so compressed substantially uniformly from end to end, subsequent treatment of the doffed strand 235 is facilitated.

The modified action of the carriage 116 in performing the compressing action on the stirred strand 115 after the clamp members 65-65 are opened is illustrated by the broken line curve 294' in FIG. 11 which shows how the groove 166 in the carriage reciprocating cam 167 is modified to cause movement different from the movement represented by the solid line curve 294. In addition the shape of the cam groove 76 in the clamp cam 77 is modified to open the clamp members 65-65 as indicated by the broken line curve 296' at such time that the opening thereof takes place before the juxtaposed end of the stirred strand 115 engages the clamp members 65-65. Accordingly, no compressing action takes place against the clamp members 65-65 when the clamp cam 77 is modified to open the clamp members 65-65 at the time indicated by curve 296' with the result that the compressing action does not start until the carriage reciprocating drum cam 167 has been rotated through about 150° from the initial position at which time the respective compressor-doffer 199 has been picked up and has been moved against the stop 200. Under such conditions the transfer of the stirred strand 115 begins shortly after the clamp members 65-65 are opened and the transfer continues throughout the remaining forward movement of the carriage 116 until the carriage jaws 119 have moved the trailing end of the stirred strand 115 past the leading end of the receiving mandrel 187 in alignment with the floating mandrel 22. Thereafter, and during the succeeding dwell period of the carriage 116 represented by the rotation of the carriage reciprocating drum cam 167 from the position at 210° to the position at approximately 260°, the clamp members 65-65 are again moved into operative position with respect to the floating mandrel 22. At this time the carriage jaws 119 hold the trailing end of the compressed strand on the receiving mandrel 187 under compression. Following this, as previously described, the receiving mandrel 187 onto which the previously stirred strand 115 has been transferred is withdrawn, as indicated by curve 297, and then the turret 177 is indexed to bring the compressor-doffer 199 into operative position with respect to the pusher 204 of the compressor means 206 which moves forwardly, as indicated in FIG. 4, to complete the compression of the partially compressed strand against the surface 202 of the compressor member 201. When the stirred strand 115 is compressed only on a receiving mandrel 187 with no compressing action taking place on the floating mandrel 22, it is unnecessary to transfer from the floating mandrel 22 to the receiving mandrel 187 in alignment therewith a partially or fully compressed strand with the result that the innermost surfaces of the folds and pleats are not required to pass the joint between the floating mandrel 22 and the receiving mandrel 187 which might lead to the abrasion of the casing sufficient to develop pin holes therein which, when the stuffing operation is performed, would lead to unsatisfactory operation.

What is claimed as new is:

1. In a machine for stirring thin walled sausage casings and the like, in combination, a floating mandrel having a leading end for extending into a tubular unshirred casing and a trailing end, means supporting said floating mandrel against endwise and sidewise movement, a stirring head in cooperative relation to said floating mandrel for stirring the casing onto the same, said floating man-

drel being substantially stationary throughout the operation of the machine, a receiving mandrel separate and distinct from said floating mandrel for receiving the shirred casing therefrom, and means for moving said receiving mandrel into and out of receiving position with respect to said floating mandrel.

2. In a machine for shirring thin walled sausage casings and the like, in combination, a floating mandrel having a leading end for extending into a tubular unshirred casing and a trailing end, clamp means supporting said floating mandrel at said trailing end against endwise and sidewise movement, a shirring head in cooperative relation to said floating mandrel for shirring the casing onto the same, means driving said shirring head for continuously shirring the casing onto said floating mandrel, means for severing a shirred strand of the casing from the following shirred casing, said floating mandrel being substantially stationary throughout the operation of the machine, a receiving mandrel separate and distinct from said floating mandrel for receiving the shirred strand therefrom, and means for moving said receiving mandrel into and out of receiving position with respect to said floating mandrel and for unclamping said clamp means from and clamping the same to said trailing end of said floating mandrel to permit transfer of the shirred strand to said receiving mandrel.

3. In a machine for shirring thin walled sausage casings and the like, in combination, a floating mandrel having a leading end for extending into a tubular unshirred casing and a trailing end, clamp means supporting said floating mandrel at said trailing end against endwise and sidewise movement, a shirring head in cooperative relation to said floating mandrel for shirring the casing onto the same, said floating mandrel being substantially stationary throughout the operation of the machine, a turret rotatable about an axis parallel with the longitudinal axis of said floating mandrel and having a plurality of uniformly circumferentially spaced endwise movable receiving mandrels bodily rotatable one by one into and out of endwise alignment with said floating mandrel, shifter means operatively connectable to said receiving mandrels one by one for moving the leading end of the receiving mandrel in alignment with said floating mandrel into endwise engagement with said trailing end thereof to hold it against endwise movement, and means for unclamping said clamp means from said trailing end of said floating mandrel after it is engaged as aforesaid by a receiving mandrel to permit transfer of the shirred casing from the former to the latter and thereafter reclamping said clamp means.

4. In a machine for shirring thin walled sausage casings and the like, in combination, a floating mandrel having a leading end for extending into a tubular unshirred casing and a trailing end, clamp means supporting said floating mandrel at said trailing end against endwise and sidewise movement, a shirring head in cooperative relation to said floating mandrel for shirring the casing onto the same, means driving said shirring head for continuously shirring the casing onto said floating mandrel, said floating mandrel being substantially stationary throughout the operation of the machine, means for severing a shirred strand of the casing from the following shirred casing, a turret rotatable about an axis parallel with the longitudinal axis of said floating mandrel and having a plurality of uniformly circumferentially spaced endwise movable receiving mandrels bodily rotatable one by one into and out of endwise alignment with said floating mandrel, shifter means operatively connectable to said receiving mandrels one by one for moving the leading end of the receiving mandrel in alignment with said floating mandrel into endwise engagement with said trailing end thereof to hold it against endwise movement, and means for unclamping said clamp means from said trailing end of said floating mandrel after it is engaged as aforesaid by a receiving mandrel to permit transfer of the shirred strand from the

former to the latter and thereafter reclamping said clamp means.

5. In a machine for shirring thin walled sausage casings and the like, in combination, a floating mandrel having a leading end for extending into a tubular unshirred casing and a trailing end, clamp means supporting said floating mandrel at said trailing end against endwise and sidewise movement, compaction means juxtaposed to said floating mandrel and spaced a predetermined distance from said leading end thereof, a shirring head in cooperative relation to said floating mandrel for shirring the casing onto the same against said compaction means, said floating mandrel being substantially stationary throughout the operation of the machine, means driving said shirring head for continuously shirring the casing, means adjacent said compaction means for periodically severing a shirred strand of the casing from the following shirred casing, a turret rotatable about an axis parallel with the longitudinal axis of said floating mandrel and having a plurality of uniformly circumferentially spaced endwise movable receiving mandrels bodily rotatable one by one into and out of endwise alignment with said floating mandrel, shifter means operatively connectable to said receiving mandrels one by one for moving the leading end of the receiving mandrel in alignment with said floating mandrel into endwise engagement with said trailing end thereof to hold it against endwise movement, and means for unclamping said clamp means from said trailing end of said floating mandrel after it is engaged as aforesaid by a receiving mandrel to permit transfer of the shirred strand from the former to the latter and thereafter reclamping said clamp means.

6. In a machine for shirring thin walled sausage casings and the like, in combination, a floating mandrel having a leading end for extending into a tubular unshirred casing and a trailing end, clamp means supporting said floating mandrel at said trailing end against endwise and sidewise movement, compaction means juxtaposed to said floating mandrel and spaced a predetermined distance from said leading end thereof, a shirring head in cooperative relation to said floating mandrel for shirring the casing onto the same against said compaction means, said floating mandrel being substantially stationary throughout the operation of the machine, means driving said shirring head for continuously shirring the casing, means adjacent said compaction means for periodically severing a shirred strand of the casing from the following shirred casing, a turret rotatable about an axis parallel with the longitudinal axis of said floating mandrel and having a plurality of uniformly circumferentially spaced endwise movable receiving mandrels bodily rotatable one by one into and out of endwise alignment with said floating mandrel, shifter means operatively connectable to said receiving mandrels one by one for moving the leading end of the receiving mandrel in alignment with said floating mandrel into endwise engagement with said trailing end thereof to hold it against endwise movement, means for unclamping said clamp means from said trailing end of said floating mandrel after it is engaged as aforesaid by a receiving mandrel, means for transferring the shirred strand from said floating mandrel after said clamp means is opened, and means reclamping said clamp means to said trailing end of said floating mandrel after the shirred strand has been transferred therefrom.

7. In a machine for shirring thin walled sausage casings and the like, in combination, a floating mandrel having a leading end for extending into a tubular unshirred casing and a trailing end, clamp means supporting said floating mandrel at said trailing end against endwise and sidewise movement, compaction means juxtaposed to said floating mandrel and spaced a predetermined distance from said leading end thereof, a shirring head in cooperative relation to said floating mandrel for shirring the casing onto the same against said compaction means, said floating mandrel being substantially stationary throughout the op-

eration of the machine, means driving said stirring head for continuously stirring the casing, means adjacent said compaction means for periodically severing a shirred strand of the casing from the following shirred casing, a turret rotatable about an axis parallel with the longitudinal axis of said floating mandrel and having a plurality of uniformly circumferentially spaced endwise movable receiving mandrels bodily rotatable one by one into and out of endwise alignment with said floating mandrel, shifter means operatively connectable to said receiving mandrels one by one for moving the leading end of the receiving mandrel in alignment with said floating mandrel into endwise engagement with said trailing end thereof to hold it against endwise movement, means for unclamping said clamp means from said trailing end of said floating mandrel after it is engaged as aforesaid by a receiving mandrel, means for transferring the shirred strand from said floating mandrel after said clamp means is opened, means reclamping said clamp means to said trailing end of said floating mandrel after the shirred strand has been transferred therefrom, means for periodically indexing said turret to move said receiving mandrels into and out of alignment with said floating mandrel, means cooperating with those receiving mandrels rotated past alignment with said floating mandrel for compressing the shirred strands thereon and holding the same under compression while said turret is being indexed, and means for doffing the completed strand from the receiving mandrel which is next to be moved into alignment with said floating mandrel.

8. In a machine for shirring thin walled sausage casings and the like, in combination, a floating mandrel having a leading end for extending into a tubular unshirred casing and a trailing end, said floating mandrel being substantially stationary throughout the operation of the machine, clamp means engageable with said trailing end of said floating mandrel to hold it against endwise movement, compaction means juxtaposed to said floating mandrel and spaced a predetermined distance from said leading end thereof, a stirring head between said leading end of said floating mandrel and said compaction means and adjacent the latter, head driving means operatively connected to said stirring head for operating it to shirr the casing on said floating mandrel against said compaction means, and means adjacent said compaction means for severing a shirred strand of the casing from the following shirred casing.

9. In a machine for shirring thin walled sausage casings and the like, in combination, a floating mandrel having a leading end for extending into a tubular unshirred casing and a trailing end, said floating mandrel being substantially stationary throughout the operation of the machine, clamp means engageable with said trailing end of said floating mandrel to hold it against endwise movement, a pair of compaction rolls on opposite sides of said floating mandrel and spaced a predetermined distance from said leading end thereof, a stirring head between said leading end of said floating mandrel and said compaction rolls, head driving means operatively connected to said stirring head for operating it to shirr the casing on said floating mandrel at a predetermined speed against said compaction rolls, and driving means connected to one of said compaction rolls to rotate it in the direction in which the casing is shirred at a peripheral speed equal to the linear speed at which the shirred casing moves along said floating mandrel.

10. In a machine for shirring thin walled sausage casings and the like, in combination, a tubular floating mandrel having a leading end for extending horizontally into a tubular unshirred casing and a trailing end, said floating mandrel being substantially stationary throughout the operation of the machine, clamp means engageable with said trailing end of said floating mandrel to hold it against endwise movement, a pair of compaction rolls on opposite sides of said floating mandrel and spaced a predetermined

mined distance from said leading end thereof, a stirring head between said leading end of said floating mandrel and said compaction rolls, a support roll underneath said leading end of said floating mandrel, head driving means operatively connected to said stirring head for operating it to shirr continuously the casing on said floating mandrel at a predetermined speed against said compaction rolls, means connecting said head driving means to one of said compaction rolls to rotate it continuously in the direction in which the casing is shirred at a peripheral speed equal to the linear speed at which the shirred casing moves along said floating mandrel, and means connecting said head driving means to said support roll to rotate it continuously in the direction in which the unshirred casing moves toward said stirring head and at a peripheral speed equal to the linear speed of the unshirred casing.

11. In combination, a mandrel onto which a thin walled sausage casing or the like is shirred and moves therealong at a predetermined speed, and a machine for severing a strand of the shirred casing from the following shirred casing while the casing moves along said mandrel, said machine including holding means for engaging the following shirred casing on said mandrel to prevent movement thereof therealong at a speed greater than said predetermined speed, means for extending a portion of the shirred casing along said mandrel away from said holding means, and means for severing the casing at said extended portion thereof.

12. In combination, a mandrel onto which a thin walled sausage casing or the like is shirred and moves therealong at a predetermined speed, and a machine for severing a strand of the shirred casing from the following shirred casing while the casing moves along said mandrel, said machine including a holding finger movable toward and away from said mandrel for engaging the following shirred casing thereon to prevent movement thereof therealong at a speed greater than said predetermined speed, a pair of pinch members bodily movable toward and away from opposite sides of said mandrel and bodily movable therealong at a speed higher than said predetermined speed away from said holding finger for extending a portion of the shirred casing therefrom, scoring means movable toward and away from said mandrel for severing the casing at said extended portion, and means for sequentially operating said holding finger, said pinch members and said scoring means.

13. The invention, as set forth in claim 12, wherein the pinch members comprise a pair of pinch rolls and means are provided for rotating them in opposite directions to reshrir the extended portion of the casing after the strand has been severed from the following shirred casing.

14. In combination, a mandrel onto which a thin walled sausage casing or the like is shirred and moves therealong at a predetermined speed, and a machine for severing a strand of the shirred casing from the following shirred casing while the casing moves along said mandrel, said machine including a holding finger movable toward and away from said mandrel for engaging the following shirred casing thereon to prevent movement thereof therealong at a speed greater than said predetermined speed, a pair of pinch members bodily movable toward and away from opposite sides of said mandrel and bodily movable therealong at a speed higher than said predetermined speed away from said holding finger for extending a portion of the shirred casing therefrom, scoring means movable toward and away from said mandrel for severing the casing at said extended portion, means for moving said holding finger and said scoring means along said mandrel at the speed that the shirred casing is moved therealong, means for sequentially moving said holding finger and said scoring means toward and away from said mandrel, and means for moving said pinch members toward said mandrel to engage the casing thereagainst and for bodily moving them away from said holding finger at said higher speed to provide said extended portion.

15. In combination, a mandrel onto which a thin walled sausage casing or the like is Shirred, means for separating adjacent folds of the Shirred casing to provide an extended portion, means for moving limited areas of said extended portion into scoring engagement with said mandrel to initiate tears therein, and means for tensioning said extended portion along said mandrel to extend said tears completely around said extended portion.

16. In combination, a mandrel onto which a thin walled sausage casing or the like is Shirred, means for separating adjacent folds of the Shirred casing to provide an extended portion, a bifurcated scoring yoke having arms movable transversely of opposite sides of said mandrel into small area scoring contact engagement with said mandrel to initiate tears in said extended portion of said casing, and means for tensioning said extended portion of said casing along said mandrel to extend said tears completely around said extended portion.

17. In combination, a substantially stationary floating mandrel onto which strands of thin walled sausage casing or the like are successively Shirred, and means for moving the strands along said mandrel including a carriage movable long said mandrel, and a pair of jaws mounted on said carriage for scissors like movement for engaging a strand on said mandrel to effect conjoint movement of said strand with said carriage.

18. In combination, a substantially stationary floating mandrel onto which strands of thin walled sausage casing or the like are successively Shirred, and means for moving the strands along said mandrel including a carriage movable along said mandrel, and a pair of jaws pivotally mounted on said carriage for scissors like movement toward and away from said mandrel to engage and disengage one end of a strand on said mandrel and effect conjoint movement of said strand with said carriage.

19. In combination, a substantially stationary floating mandrel onto which strands of thin walled sausage casing or the like are successively Shirred, and means for moving the strands along said mandrel including a pair of support rails in parallel spaced relation to and extending along said mandrel, means supporting said rails for rotation about their longitudinal axes, a carriage movably mounted on said rails, a pair of jaws pivotally mounted on said carriage for scissors like movement toward and away from each other and said mandrel to engage and disengage one end of a strand on said mandrel and effect conjoint movement of said strand with said carriage, means operatively interconnecting said jaws and one of said support rails to effect the aforesaid scissors like movement of said jaws on rotation of said one support rail about its longitudinal axis, means mounting said jaws on said carriage for sidewise movement toward and away from said mandrel, means operatively interconnecting said jaws and the other of said support rails to effect the aforesaid sidewise movement of said jaws on rotation of said other support rail about its longitudinal axis, and means for rotating said support rails about their longitudinal axes to operate said pair of jaws as aforesaid.

20. In combination, a substantially stationary tubular floating mandrel having a leading end over which a thin walled sausage casing or the like moves to be Shirred and a trailing end, clamp means detachably engaging said trailing end and cooperating therewith to hold said floating mandrel stationary, said clamp means having an air passageway communicating with the opening in said tubular floating mandrel through which air under pressure can be supplied to inflate the casing at said leading end, a tubular receiving mandrel movable into endwise supporting alignment with said trailing end and cooperating with said floating mandrel to hold it stationary when said clamp means is unclamped therefrom, the opening through said tubular receiving mandrel through which air under pressure can be supplied communicating with said opening through said floating mandrel to maintain the flow of air

under pressure at said leading end, and valve means for placing said opening through said floating mandrel in communication with said air passageway in said clamp means or with said opening through said receiving mandrel depending upon whether the air is supplied under pressure through said clamp means or through said receiving mandrel.

21. In combination, a tubular floating mandrel having a leading end over which a thin walled sausage casing or the like moves to be Shirred and a trailing end, clamp means detachably engaging said trailing end and cooperating therewith to hold said floating mandrel stationary, said clamp means having an air passageway communicating with the opening in said tubular floating mandrel through which air under pressure can be supplied to inflate the casing at said leading end, a tubular receiving mandrel movable into endwise supporting alignment with said trailing end and cooperating with said floating mandrel to hold it stationary when said clamp means is unclamped therefrom, a tubular connector extending endwise from said trailing end of said floating mandrel and interfitting with said receiving mandrel and placing the opening therethrough through which air under pressure can be supplied in communication with said opening through said floating mandrel to maintain the flow of air under pressure at said leading end, and valve means within said trailing end of said floating mandrel for placing said opening therethrough in communication with said air passageway in said clamp means or with the opening through said tubular connector depending upon whether the air is supplied under pressure through said clamp means or through said receiving mandrel.

22. In combination, a substantially stationary floating mandrel having a leading end over which a thin walled sausage casing or the like moves to be Shirred and a trailing end, clamp means supporting said floating mandrel at said trailing end against movement, a turret having a plurality of receiving mandrels movable one by one into and out of endwise alignment with said floating mandrel, means for operating said turret in a stepwise fashion to move said receiving mandrels into alignment with said floating mandrel, and means for unclamping said clamp means when a receiving mandrel is in endwise alignment with said floating mandrel.

23. In combination, a substantially stationary floating mandrel having a leading end over which a thin walled sausage casing or the like moves to be Shirred and a trailing end, clamp means supporting said floating mandrel at said trailing end against movement, a turret having a plurality of endwise movable receiving mandrels bodily movable one by one into and out of endwise alignment with said floating mandrel, means for operating said turret in a stepwise fashion to move said receiving mandrels into alignment with said floating mandrel, means for shifting endwise the receiving mandrel in alignment with said floating mandrel into supporting relation with said trailing end thereof, and means for unclamping said clamp means when a receiving mandrel is moved into supporting relation with said floating mandrel.

24. In combination, a substantially stationary floating mandrel onto which strands of thin walled sausage casing or the like are successively Shirred in one direction, means for compressing a Shirred strand on said floating mandrel in the direction that the casing is Shirred thereon, and means for compressing the Shirred strand on said floating mandrel in the opposite direction.

25. In combination, a substantially stationary floating mandrel onto which strands of thin walled sausage casing or the like are successively Shirred in one direction, means for partially compressing a Shirred strand on said floating mandrel in the direction that the casing is Shirred thereon, and means for completing the compression of the Shirred strand on said floating mandrel in the opposite direction.

26. In combination, a substantially stationary floating

mandrel onto which strands of thin walled sausage casing or the like are successively shirred toward one end, clamp means at said one end of said floating mandrel holding it stationary, a receiving mandrel movable into and out of endwise supporting relation with said one end of said floating mandrel, means for unclamping said clamp means when said receiving mandrel supports said floating mandrel, means for transferring a shirred strand from said floating mandrel to said receiving mandrel, and means for compressing the shirred strand on said receiving mandrel.

27. In combination, a substantially stationary floating mandrel onto which strands of thin walled sausage casing or the like are successively shirred toward one end, clamp means at said one end of said floating mandrel holding it stationary, means for engaging the end of a shirred strand remote from said one end of said floating mandrel to compress the shirred strand against said clamp means, a receiving mandrel movable into and out of endwise supporting relation with said one end of said floating mandrel, means for unclamping said clamp means when said receiving mandrel supports said floating mandrel, means for transferring the compressed strand from said floating mandrel to said receiving mandrel, and means for engaging the other end of the shirred and compressed strand on said receiving mandrel for compressing it in the direction opposite to the direction in which it was compressed against said clamp means.

28. In combination, a substantially stationary floating mandrel onto which strands of thin walled sausage casing or the like are successively shirred toward one end, clamp means at said one end of said floating mandrel holding it stationary, a receiving mandrel movable into and out of endwise supporting relation with said one end of said floating mandrel, means for unclamping said clamp means when said receiving mandrel supports said floating mandrel, means on said receiving mandrel providing a surface against which a shirred strand can be compressed, means for engaging the end of the shirred strand remote from said one end of said floating mandrel to transfer the strand therefrom to said receiving mandrel when said clamp means is unclamped to cause the other end of the shirred strand to engage said surface and to compress the shirred strand against said surface, means providing a second surface against which the shirred and compressed strand can be compressed, and means for engaging said other end of the strand to cause said one end thereof to engage said second surface and to compress the shirred and compressed strand against said second surface.

29. In combination, a substantially stationary floating mandrel onto which strands of thin walled sausage casing or the like are successively shirred toward one end, clamp means at said one end of said floating mandrel holding it stationary, a receiving mandrel movable into and out of endwise supporting relation with said one end of said floating mandrel, means for unclamping said clamp means when said receiving mandrel supports said floating mandrel, means on said receiving mandrel providing a surface against which a shirred strand can be compressed, means for engaging the end of the shirred strand remote from said one end of said floating mandrel to transfer the strand therefrom to said receiving mandrel when said clamp means is unclamped to cause the other end of the shirred strand to engage said surface and to compress the shirred strand against said surface, means providing a second surface against which the shirred and compressed strand can be compressed, means for moving said receiving mandrel after said clamp means has been clamped with the shirred and compressed strand thereon into operative relation with respect to said second surface, and means for engaging said other end of the strand to cause said one end thereof to engage said second surface and to compress the shirred and compressed strand against said second surface.

30. In a machine for shirring thin walled sausage cas-

ings and the like, in combination, a floating mandrel having a leading end and a trailing end, means reciprocable along said floating mandrel for engaging a shirred strand of casing and disengaging it from said trailing end, a 5 rotatable turret having a plurality of uniformly spaced receiving mandrels rotatable successively into and out of endwise engagement with said floating mandrel, a compressor-doffer slideable endwise on each receiving mandrel; shifter means operatively connectable to said receiving mandrels successively for moving the leading end 10 of the receiving mandrel in alignment with said floating mandrel into endwise engagement with the trailing end of said floating mandrel to hold it against endwise movement, to receive the compressed and shirred strand, and 15 to retract the last named receiving mandrel out of engagement with said trailing end after receiving said compressed and shirred strand; a compressor member having a compressor surface juxtaposed to the leading ends of those receiving mandrels rotated past alignment with said 20 floating mandrel, clamp means engageable with said trailing end of said floating mandrel to hold it against endwise movement, compressor means operatively connectable to said compressor-doffers successively for moving the same toward said compressor member to compress the shirred strand therebetween, a holding member having a holding 25 surface cooperating to hold the compressor-doffers stationary on said receiving mandrel while said turret is rotated, doffer means for moving said compressor-doffers successively to doff a completed strand from the leading 30 end of the receiving mandrel, machine driving means operatively connected to said reciprocable means to reciprocate it periodically to engage endwise a shirred strand on said floating mandrel and on movement to compress the shirred strand thereon against said clamp means, and 35 after engagement thereof from said floating mandrel to transfer the compressed and shirred strand to the receiving mandrel in alignment therewith, means connecting said turret to said machine driving means to index it in one direction about its axis of rotation to cause said receiving mandrels to move successively into endwise axial engagement with said floating mandrel, means connecting said shifter means to said machine driving means for moving the receiving mandrel in alignment with said floating mandrel into and out of endwise supporting engagement therewith, means connecting said clamp means 40 to said machine driving means for opening the same while said floating mandrel is held against movement and the compressed and shirred strand is transferred, and thereafter to re-engage and hold said trailing end of said floating mandrel, means connected to said machine driving means for controlling the operation of said compressor means for moving the compressor-doffer on the receiving mandrel in its next indexed position after alignment with said floating mandrel toward said compressor surface to 45 further compress the compressed and shirred strand thereagainst, said last named compressor-doffer being moved beyond said holding surface by said compressor means whereby said last mentioned compressor-doffer reacts against said holding surface on subsequent indexing of said turret, and means connected to said machine driving means for controlling the operation of said doffer means to move the compressor-doffer and doff the completed strand from the receiving mandrel whose next indexed position is in alignment with said floating mandrel.

50 31. A machine according to claim 30 in which said reciprocable means comprises a carriage reciprocable along said floating mandrel between an initial position intermediate the ends of said floating mandrel and a terminal position beyond the trailing end thereof, and jaw 55 means on said carriage for engaging in said initial position a shirred strand and disengaging it in said terminal position, said clamp means comprising a pair of separable clamps engageable with the trailing end of said floating mandrel to hold the same against endwise movement, 60 and means connecting said jaw means on said carriage to 65 said receiving mandrel.

70 32. A machine according to claim 30 in which said reciprocable means comprises a carriage reciprocable along said floating mandrel between an initial position intermediate the ends of said floating mandrel and a terminal position beyond the trailing end thereof, and jaw 75 means on said carriage for engaging in said initial position a shirred strand and disengaging it in said terminal position, said clamp means comprising a pair of separable clamps engageable with the trailing end of said floating mandrel to hold the same against endwise movement, and means connecting said jaw means on said carriage to

said machine driving means to close in said initial position of said carriage into juxtaposition with said floating mandrel and engage endwise the severed end of the stirred strand and on movement of said carriage toward said terminal position to compress the stirred strand against said clamps and after disengagement of said clamps to transfer the compressed and stirred strand to the receiving mandrel in alignment with said floating mandrel, and said jaw means being subsequently opened in said terminal position of said carriage by said machine driving means and moved out of interfering relation with said clamp means after it is closed and while said carriage is being moved from said terminal position to said initial position.

32. A machine according to claim 30 which includes compaction means juxtaposed to said floating mandrel and spaced a predetermined distance from the leading end thereof, a stirring head between said leading end of said floating mandrel and said compaction means, head driving means operatively connected to said stirring head for operating the same to stir the casing on said floating mandrel against said compaction means, means adjacent said compaction means for severing a stirred strand of the casing from the following stirred casing, means for supplying air under pressure to the receiving mandrel in alignment with said floating mandrel when said receiving mandrel is moved into engagement therewith by said shifter means, to supply compressed air through said floating mandrel for maintaining the casing inflated, clamp means engageable with said trailing end of said floating mandrel to hold the same against endwise movement, means for supplying air under pressure through said clamp means into said floating mandrel for inflating the casing prior to stirring, and means operatively connecting said machine driving means to said severing means for periodically detaching a stirred strand from the previously stirred casing.

33. A machine according to claim 32 in which said compaction means comprises a pair of compaction rolls on opposite sides of said floating mandrel and spaced a predetermined distance from the leading end thereof, said stirring head being positioned between said leading end of said floating mandrel and said compaction rolls and operated by said head driving means to stir casing on said floating mandrel at a predetermined speed against said compaction rolls, means connecting said head driving means to one of said compaction rolls to rotate it in the direction in which the casing is stirred at a peripheral speed equal to the linear speed at which the stirred casing moves along said floating mandrel, a carriage reciprocable along said floating mandrel between an initial position adjacent said severing means and a terminal position beyond the trailing end of said floating mandrel, jaw means on said carriage for endwise engaging the stirred strand in said initial position and disengaging the stirred strand in said terminal position, means connecting said carriage to said machine driving means to reciprocate the same periodically between said initial and terminal positions in timed relation to the operation of said strand severing means, means connecting said jaw means on said carriage to said machine driving means to close in said initial position of said carriage into juxtaposition with said floating mandrel and engage endwise the severed end of the stirred strand and on movement of said carriage toward said terminal position to compress the stirred strand against said clamp means and after disengagement thereof to transfer the compressed and stirred

strand to the receiving mandrel in alignment with said floating mandrel, said jaw means being subsequently opened in said terminal position of said carriage by said machine driving means and moved out of interfering relation with said clamp means after it is closed and while said carriage is being moved from said terminal position to said initial position.

34. A machine in accordance with claim 32 in which said compaction means comprises a pair of compaction rolls on opposite sides of said floating mandrel and spaced a predetermined distance from said leading end thereof, a support roll underneath the leading end of said floating mandrel, said head driving means being operatively connected to said stirring head for operating it to stir continuously the casing on said floating mandrel at a predetermined speed against said compaction rolls, and operatively connected to one of said compaction rolls to rotate it continuously in the direction in which the casing is stirred at a peripheral speed equal to the linear speed at which the stirred casing moves along said floating mandrel, said head driving means being operatively connected to said support roll to rotate it continuously in the direction in which the unstirred casing moves toward said stirring head and at a peripheral speed equal to the linear speed of the unstirred casing, a carriage reciprocable along said floating mandrel between an initial position adjacent said severing means and a terminal position beyond the trailing end of said floating mandrel, jaw means on said carriage for endwise engaging the stirred strand in said initial position and disengaging the stirred strand in said terminal position, a pair of separable clamps engageable with said trailing end of said floating mandrel to hold it against endwise and transverse movement, means for supplying air under pressure through one of said clamps into said floating mandrel for inflating the casing before it is stirred, means connecting said carriage to said machine driving means to reciprocate it periodically between said initial and terminal positions in timed operation to the operation of said strand severing means, means connecting said jaw means on said carriage to said machine driving means to close in said initial position of said carriage into juxtaposition to said floating mandrel and endwise engage the severed end of the stirred strand and on movement of said carriage toward said terminal position to compress the stirred strand against said clamps and after disengagement of said clamps to transfer the compressed and stirred strand to the receiving mandrel in alignment with said floating mandrel, said jaw means being subsequently opened in said terminal position of said carriage by said machine driving means and moved out of interfering relation with said clamps after they are closed and while said carriage is being moved from said terminal position to said initial position and motor means operatively connected to said head driving means and to said machine driving means for simultaneous and continuous operation thereof.
